MULTIPLE IMPRESSION PRINTING APPARATUS AND METHOD

Emil Ericksson, Chicago, Ill., assignor to Standard Process Corporation, Chicago, Ill., a corporation of Delaware

Application September 22, 1932, Serial No. 634,406

26 Claims. (Cl. 101—152)

My present invention relates to printing apparatus and method and more particularly to a novel single or multiple impression printing press and printing method and web heating and drying methods and means, and web roll supporting and web tensioning means.

In accordance with my invention one, or a number of impressions may be had on a surface to be printed upon, in accurate location on the surface and in perfect juxtaposition, the material, the surface of which has received the impression or impressions, being treated by my novel means in accordance with my novel method.

Therefore the primary object of my invention is the provision of novel methods and apparatus for printing on and treating a surface to produce accurately positioned impressions.

A further object of my invention is the provision of novel methods and apparatus for printing on and treating a surface to produce accurately positioned impressions or impression continuously and to maintain the accurate positioning during the continuous production of the impressions or impression.

Another object of my invention is to provide a novel printing press in combination with web feeding and treating means whereby a web may receive accurately positioned impressions or impression.

Still another object of the invention is to provide a novel printing press having a plurality of printing means of my invention, in combination with interposed means for drying and treating the printed surface to permit successive superimposed printing on the same portion of the surface with all the impressions of the successive printings in exact and accurate coincidence or register.

A further object of my invention is to provide a novel printing press having an impression cylinder free to rotate, and a plurality of driven printing surfaces circular in cross section spaced about the impression cylinder to advance and print upon a web maintained under proper tension.

A still further object of my invention lies in the provision of a method of drying by projecting a drying fluid onto the material to be dried and immediately withdrawing the drying fluid.

A still further object of my invention lies in the provision of a method of drying the ink on a printed surface quickly and effectively by heating the inked surface and cooling it to crystallize the ink.

A still further object of my invention lies in the

provision of a method of drying the ink on a printed surface by continuous projection of heated and cooled fluid onto the surface and immediate and continuous withdrawal of the heated and cooled fluid and fumes from the surface.

A still further object of my invention is to provide a novel printing press having an impression surface, and printing surfaces movable toward and from the impression surface collectively or individually.

A still further object of my invention is to provide a novel printing press having an impression surface and printing surfaces the pressure of which may be altered on the impression surface and which may be moved toward and away from the impression surface collectively or individually and when moved toward the impression surface will press thereagainst with the desired selected pressure.

A still further object of my invention is to provide a novel printing press having a plurality of movable printing cylinders which may be moved toward and away from an impression cylinder collectively or individually and means to supply ink to the printing cylinders when they are in contact or out of contact with the impression cylinder, whereby the ink may be maintained fresh and of the proper consistency.

A still further object of my invention is to provide a novel printing press having an impression cylinder and printing cylinders for operative printing contact therewith spaced about said impression cylinder, one of the printing cylinders being movable bodily to expose said impression cylinder so that it may be conveniently resurfaced or removed bodily.

A still further object of my invention is to provide a novel printing press having a freely rotatable impression cylinder and positively driven printing cylinders from which rotation is imparted to said impression cylinder to propel a web therebetween and means to initially start and accelerate said impression cylinder to prevent tearing or distortion of the web.

A still further object of my invention is to provide a printing cylinder adapted to receive a printing shell and means to apply and remove said shell with the printing cylinder in operative position in the press.

A still further object of my invention is to provide a novel means for variably reciprocating a doctor blade whereby the doctor blade moves over different parts of the printing cylinder to avoid scoring.

A still further object of my invention is to pro-

- vide a novel printing cylinder mandrel for retaining a printing shell firmly in position thereon without distortion by uniform expansion of the mandrel.
- 5 A still further object of my invention is to provide a novel web reel holder including web tensioning means, web guide and web reel handling means.
- 10 Other objects of the invention will appear in the following disclosure of the preferred embodiments and preferred methods.
- In the drawings:
- Figure 1 is a side-elevational view of a preferred embodiment of my invention illustrating the printing press in section and the web roll and final drying stand, in which the front part of the press is shown to the right of the drawing.
- Figure 2 is a front view of the embodiment of the web reel and drying stand of Figure 1.
- 20 Figure 3 is a front view in elevation of the embodiment of the press shown in Figure 1.
- Figure 4 is a left side elevation thereof.
- Figure 5 is a right side elevation of the embodiment of the press shown in Figure 1.
- 25 Figure 6 is a fragmentary sectional view on line 6—6 of Figure 4, illustrating in detail the novel mechanism for moving the printing rolls into and out of operative printing position collectively or individually.
- 30 Figure 7 is a large scale fragmentary view in section on line 7—7 of Figure 5 showing the printing cylinder registering mechanism.
- Figures 8 and 9 are top plan and elevational views of a detail of Figure 7.
- 35 Figure 10 is a detailed showing of certain of the parts of Figure 7 in elevation.
- Figure 11 is a section upon line 11—11 of Figure 1, showing the details of the novel printing cylinder mandrel of my invention.
- 40 Figure 12 is an end view of the mandrel of Figure 11.
- Figure 13 is a fragmentary sectional view in right side elevation of the mechanism for initially starting the impression cylinder and accelerating it to the desired operating speeds.
- 45 Figure 14 is a fragmentary sectional view of the main driving means.
- Figure 15 is a cross sectional view in elevation of the ink distributor.
- 50 Figures 16 and 17 are side and front views in elevation illustrating the ink supply means for a printing cylinder.
- Figure 18 is a top plan view showing the arrangement of the ink and cleansing fluid supply reservoirs and the preferred mode of interconnecting them.
- 55 Figure 19 is a side elevation of the parts appearing in Figure 18, some of the conduits being omitted in the interest of clearness of illustration.
- 60 Figure 20 is a detailed showing of my novel means for collective reciprocation of the ink wiping means and illustrates also the printing cylinder support rods.
- Figure 21 is a side-elevational view in detail of the mechanism appearing in the lower part of Figure 20, one half of the casing being removed to illustrate the mechanism.
- 65 Figure 22 is a front-elevational view in section on line 22—22 of the mechanism of Figure 21.
- 70 Figures 23 and 24 are rear and side-elevational views of an embodiment of the novel drying means.
- Figure 25 is a top plan view of the embodiment of the novel drying means illustrated in Figure 1.
- 75 Referring to the drawings and for the present particularly to Figures 1 to 5, wherein are illustrated a preferred embodiment of a printing press, indicated generally by reference character 11, which I will now describe and point out the operation thereof, along with web reel stand or paper holder 12 to be described hereinafter somewhat more fully.
- Press 11 is provided with a normally idling impression cylinder 13 having a suitable impression surface 14, preferably of a yielding substance such as rubber or the like. Spaced about the periphery of impression cylinder 13 are mandrels or printing cylinder holders 16, 18, 19 and 21 which receive readily removable, thin printing cylinders or shells 22, held firmly on mandrel 15 by a novel means yet to be described. The shells 22, and the methods of forming and utilizing them, are fully disclosed and claimed in my copending applications Serial Numbers 413,916 and 525,267. It is of course obvious that if desired cylinders 16, 18, 20 19, and 21 may themselves be provided with engraved or relief printing surfaces or may receive movable type if so desired, and this arrangement may be varied at will to produce successive superimposed impressions on the same area of printing surface from each of cylinders 16, 18, 19 and 21 by any known printing or transfer means. Different colors or the same color may be printed by each of cylinders 16, 18, 19 and 21 if desired.
- Web 23, which may be of any substance upon the surface of which it is desired to print, either paper or textile material, is passed from material rolls 24 or 26 through guide rolls 27—27 and over roller 28 under proper tension, regulated by tensioning means indicated generally by reference character 29 which is to be described. Web 23 prior to its entry between the printing couples formed by impression surface 14 and printing cylinders 22 is guided by pairs of adjustable tensioning rolls 30—30 and 31—31 carried by adjusting means to be hereinafter described, and guide rolls 32, 33 and 34. Web 23 after passing between the final printing couple comprising cylinder 21 and impression surface 14 is guided over roll 35 after which it may pass back over the top of web roll stand 12 if desired for final treatment by the web drying and treating means thereon and wound or otherwise conveniently taken care of by any desired means not shown which draws it under desired tension from press 11 through the final treating means. Guide rollers 32, 33 and 35 are supported for adjustment from an adjustable support to be described somewhat in detail at a later point herein in connection with the detailed description of the web tensioning and feeding means.
- I will now proceed with a detailed description of the mechanism of the preferred embodiment of the press with particular reference to Figures 3, 4 and 5 of the drawings.
- General description of the press*
- As best shown on Figure 3 two frames 38 and 39 and an outside auxiliary frame 41 are positioned on a base or sole plate 42. Frames 38 and 39 are provided with four apertures 43 positioned so that when frames 38 and 39 are mounted on sole plate 42, the apertures are opposite each other. A corner of each one of apertures 43 is provided with a web 44 which is made integral with frames 38 and 39.
- As illustrated on Figure 1, printing cylinder mandrels 16, 18, 19 and 21 are supported at spaced points about the periphery of impression cylinder 13 by a novel means shown to an en-

larged scale by Figure 7, whereby the surface of each printing cylinder 22 may be moved individually or collectively into and out of contact with impression surface 14 of impression cylinder 13 so that any one or all of printing cylinders 22 may be used at the will of the operator for printing on web 23.

Bearings 46 and 47 for printing cylinder shafts 48, 49, 51 and 52 are rotatably mounted on bearings 53 and 54 carried by swingable bearing frames or housings 56 and 57, which are pivotally mounted on bosses 44 by means of stub shafts 58 and 59 in frame members 38 and 39 respectively. Bearing carrying frames 56 are made up of two parts 61 and 62 placed back to back and held together by suitable fastening or clamping means, for example, by bolts 63. Frames 57 are made up in a like manner of parts 64 and 66 held back to back by suitable clamping means. Parts 61 and 62 of swingable bearing frame 56 and parts 64 and 66 of swingable frame 57 form bifurcated portions which fit over and contact with bosses 44 which together with shafts 58 and 59 form a pivot joint which, while permitting frames 56 and 57 to swing freely prevent twisting or lateral movement thereof, and thus prevent inaccuracies in the register of printing cylinders 16, 18, 19 and 21. Frames 56 are provided at their ends opposite pivot points 58 with apertured projections 67 and 68 provided with apertures 69 for connection with a means about to be described, for moving printing cylinders 16, 18, 19 and 21 selectively or collectively into and out of contact with impression surface 14 of impression cylinder 13. Frames 57 are provided with projections 71 and 72, apertured at 69 for a like purpose.

Arrangement for moving printing cylinders on and off impression

Movement is imparted to frames 56 and 57 from shafts 73 (Figure 6) by means of links 74 connected thereto by pins 75 received in apertures 69 of extensions 67 and 68, and extensions 71 and 72. It is to be understood that a shaft 73 is provided for each of the printing cylinders. Shafts 73 are rotatably journaled in bosses 76 and 77 of brackets 78 and 79 on main frame member 38 and bosses 76 and 77 of brackets 80 and 82 on main frame member 39. Shafts 73 are provided with eccentric portions 83 between bosses 76 and 77 of brackets 78 and 79 to which links 74 are connected so that upon rotation of shaft 73 frame 56 will be oscillated about stub-shafts 58 to move printing cylinders 16, 18, 19 and 21 toward or from web 23 overlying impression surface 14 in accordance with the direction and degree of rotation of shaft 73. Bearing caps 84 connected to link 74 by suitable fastening means, for example bolts 86, provide for disconnection of links 74 from eccentric 83 when desired. An eccentric 83 between bosses 76 and 77 and brackets 80 and 81 is connected by links 74 in the manner just described in connection with frame 56 to impart movement simultaneously with the movement of frame 56 to frame 57 upon rotation of shaft 73 and eccentric 83 so that frames 56 and 57 may move together.

Shafts 73 may be rotated simultaneously for collective movement of printing cylinders 16, 18, 19 and 21 into and out of contact with web 23 overlying impression surface 14 by manually rotating hand wheel 89 which in turn rotates gears 91 and 92 connected to shafts 88 and 93 respec-

tively by suitable means as pins. Hand wheel 89 is connected to shaft 93 by suitable means as pin 96.

Shaft 93 is journaled for rotation in frame member 38 and is retained in position longitudinally by gear 92 and collar 97 which may be removably secured thereto by pin 98. Power driven means may also be provided for rotating shaft 88 which power means may comprise worm 98 and worm wheel 99. Worm 98 is journaled in a jacket 101 secured to frame member 38. A sleeve 103 provided with a suitable bushing of anti-friction material 104 is provided with pinion teeth 105 to mesh with the teeth of a large gear 106 secured to reduced portion 108 of shaft 109 by means of a pin 111. Worm wheel 99 is keyed to sleeve 103 by suitable means for example key 112. Sleeve 103 is retained in position longitudinally on shaft 88 between boss 113 on frame member 38 and collar 114 which may be secured to shaft 88 by pin 116.

From the mechanism thus far described it will be seen that gear 106 may rotate shaft 109 from power driven worm 98 through worm wheel 99, sleeve 103, and pinion 105.

If manual operation by hand wheel 89 is desired, pin 117 may be inserted through sleeve 103 in shaft 88 so that upon rotation of hand wheel 89, shaft 88 and pinion 105 will be rotated through gears 91 and 92. In the case of manual operation, the power driven worm 98 will be disconnected from the worm wheel 99.

Keyed to shaft 109 or otherwise secured thereto for rotation therewith is a member 118 provided with openings 119 and openings 121 of reduced diameter axially aligned with openings 119. A second set of openings 122 (Figure 4) are provided in member 118 and aligned therewith are openings 123 of reduced diameter on the side of member 118 opposite openings 121. Links 40 126, 127, 128 and 129 operatively connect member 118 through a mechanism 130 to be described in detail associated with each of the shaft 73 for simultaneous rotation of shafts 73 and hence collective movement of printing cylinders 16, 18, 45 19 and 21 into and out of contact with impression surface 14.

Links 126 and 128 are provided with anti-friction linings or bushings 131 to receive bolts 132 which provide a pivotal connection of links 126 and 128 to member 118. Large diameter shanks 133 of bolts 132 are received in apertures 119 in member 118. Shank portions 134 of smaller diameter are received in apertures 121 so that nuts 136 may serve to clamp the ends of shank 55 133 against the bottoms of apertures 119 leaving the links free for movement between member 118 and the heads of bolts 132. Links 127 and 129 are connected in a similar manner to member 118 by means of bolts 132 threaded in aligned apertures 122 and 123.

It is to be understood that each of links 126, 127, 128 and 129 are connected to each of the several shafts 73 through a separate mechanism 130. However, for the sake of more conveniently disclosing my invention, I will describe the connection of link 126 to connecting and adjusting mechanism 130 for printing cylinder 16 illustrated on Figure 6.

Link 126, which operatively connects member 70 118 to mechanism 130 for simultaneous movement of shaft 73 will be selected as an example for the purpose of fully describing the means for moving printing cylinder 16 into and out of operative contact with web 23 overlying impression surface 75

14. It will be understood that links 127, 128 and 129 function simultaneously with link 126 to simultaneously operate printing cylinders 16, 18, 19 and 21.

5 Link 126 at the end opposite its connection to member 118 just described is connected by bolt 138 in aligned apertures 141 and 142. Member 143 is journaled over portion 144 of shaft 73 extending beyond bracket 78. A nut 146 serves 10 to draw the enlarged shank of bolt 138 against the bottom of aperture 141 in the manner previously described in connection with the joining of link 126 to member 118. Shaft 147 is journaled in bearing aperture of yokes 148 and 149. Worm 151 is keyed to shaft 147 by means of key 152. A collar 153 is provided outside of yoke 148 on shaft 147. Worm 151 is firmly positioned between arms 148 and 149 so that end play is prevented. Worm 151 is free to be rotated by shaft 20 147. Shaft 147 may be manually operated by any suitable means as for example key or wrench inserted in bore 154 (Figure 4). Worm teeth 156 are provided on worm wheel and clutch member 157 which mesh with worm 151. Recess 158 25 of worm wheel 157 is received over a cylindrical projection 159 of member 143. Body member or hub 161 of hand wheel 162 is provided with a recess 163 which receives cylindrical projection 164 of worm wheel 157. Hub 161 of hand wheel 162 is secured to shaft 144 by means of key 168 so 30 that shaft 144 is constrained to rotate with hub 161. Hand wheel body 161 is provided with a bore 169 extending through a cylindrical recess 171. Clutch pin 172 is inserted in bore 169. Portion 173 of large diameter of clutch pin 172 35 is received and fits within recess 171 in hub body 161. Clutch pin 169 extends beyond hub body 161 to receive hub 176 of wrench or key 177. Hub 176 is secured to pin 169 by means of a dowel 40 pin 178. The large cylindrical portion 173 of pin 169 fits within arcuate notch 181 in the periphery of cylindrical projection 164 of worm wheel 157, so that rotational movement of worm wheel 157 is transmitted to hub body 161 and 45 shaft 144.

Cylindrical portion 173 of clutch pin 172 is provided with a notch 183 extending from its end rearwardly of a width equal to or slightly greater than the width of cylindrical projection 164. Pin 50 173 may be rotated by means of key or wrench 177 to position notch 183 so that cylindrical portion 164 of worm 157 may rotate freely within recess 163 of hub 161.

The mechanism of Figure 6 just described operates in the following manner to move printing cylinders 16, 18, 19 and 21 into and out of contact with web 23 individually or collectively and to change the pressure of any one of the printing cylinders on web 23 independently.

60 Assuming that the printing cylinders are out of contact with web 23 and it is desired to simultaneously move all of the printing cylinders into operative printing contact with web 23, hand wheel 89 is rotated which imparts rotation to shaft 109. If desired, power means described above comprising worm 98 and worm wheel 99 may be used to impart rotation to shaft 109. Rotation of member 118 with shaft 109 imparts equal increments of rotational movement to 65 70 members 143, one of which is associated with each of shafts 73.

It will be seen that links 126, 127, 128 and 129 form a toggle with the radius of member 118 passing through the center of their respective 75 connecting bolts 132, so that when printing cylin-

ders 16, 18, 19 and 21 are in contact with web 23, small rotational movements of member 118 will not materially affect the contact pressure of any one of printing cylinders 16, 18, 19 and 21 with web 23, so that impressions of constant intensity may be had on web 23, a feature which is of very great advantage. The toggle action of the levers also increases the pressure of the cylinders as the toggles approach their set position.

Rotation of member 143 by its associated links 10 causes rotation of recessed worm wheel 157 by reason of engagement with helical worm 151 with the worm teeth 156.

Assuming portion 173 of pin 172 to be engaged in notch 181 in the periphery of projection 164, 15 it will be seen that hand wheel hub 161 will impart rotation to shaft 144 and eccentric portions 83, which will in turn impart swinging movements to the frames 56 and 57 carrying printing cylinder shaft 48.

Should it be desired to vary the pressure on web 23 of any one of printing cylinders 16, 18, 19 and 21, independently of the other, for example, printing cylinder 16, worm 151 may be turned by means of a wrench in bore 154 to 25 rotate worm wheel 157 while member 143 is stationary. This movement of worm wheel 157 is imparted to eccentric means 83 through cylindrical clutch member 173, engaged in notch 181, hub 161 and key 168 to shaft 144.

Should it be desired at any time, any one of the printing cylinders, for example printing cylinder 16, may be rapidly thrown into or out of operative contact with web 23 by rotating clutch member 173 by means of key 177 until notch 183 35 is positioned to clear the periphery of cylindrical projection 164, so that hand wheel 162 may be used to rotate shaft 144 free of member 143 which is retained in a stationary position by means of its associated link.

Registering mechanism

When printing from any one of printing cylinders 16, 18, 19, and 21 the impression therefrom may be positioned on a predetermined part of the 45 area of the surface to be printed upon by the novel mechanism about to be described. It is essential when printing from two or more of the cylinders that the impressions from the cylinders be perfectly superimposed and accurately 50 arranged, or in other words be in accurate and perfect register. In the novel press of my invention this accurate and perfect register may be obtained initially with the machine at rest or at full operating speed and may thereafter be adjusted during operation of the press at full operating speed.

I will now describe in detail my novel means for procuring perfect positioning of any of the 55 printed impressions from any one of printing cylinders 16, 18, 19, and 21 of perfect register of impressions from any two or more cylinders printing in succession on a common area of the material which is to be printed upon.

Referring to Figures 5 and 7, auxiliary frame 41 65 supports the ends of stub-shafts 59 previously referred to which carry frames 56 and 57. The stub-shafts are journaled in web or projection 184 of auxiliary frame 41. Web projection 184 opposite printing cylinder 21 is formed on a detachable portion 186 of auxiliary frame 41 for a purpose to be described. Swinging brackets 187 are provided with bifurcations 188 which fit over web 184 and are secured to shaft 159 by means 70 of pins 189.

Printing cylinders 16, 18, 19 and 21 advance material 23 which is to receive an impression or impressions therefrom in a novel manner and are driven by novel means which include intermediate printing cylinder drive gears 191 keyed or otherwise secured to sleeve 192 which rotates on bearing bushing or sleeve 193 on shaft 59 between arms 57 and brackets 187. Suitable means 194 provide for a supply of lubricant to the bearing surfaces on shaft 59. The several printing cylinder drive gears 191 mesh with and are driven by gear 195 which is keyed by suitable means, as key 196, or otherwise associated in driving relationship with hollow shaft 197 (Figure 13) which 10 hollow shaft is supported at one end in bearing 198 in main frame member 39, and at the other end by a mechanism 199 including brake drum 201 for a purpose to be described.

Gear 195 is driven from main drive pulley 202 20 and pinion 203 which are keyed or otherwise rotatably secured on main drive shaft 204. Bevel pinion 205 on one end of shaft 204 provides means for driving the mechanism to be described for imparting variable reciprocation to the doctor blades. A hand wheel 206 (Figure 3) is keyed or otherwise secured to main drive shaft 204 so that the mechanism of press 11 may be manually moved for the purpose of threading web 23 under the printing cylinder or to move the printing 25 cylinder or web 23 for any purpose for example when making any of the adjustments, provision for which is described herein. Intermediate cylinder drive gears 191 just described are in mesh with and impart rotation to printing cylinder 30 drive gears 207, one of which is associated with each printing cylinder 16, 18, 19 and 21.

It will be understood that a separate gear 191 and 207 drives each one of the printing cylinders whatever their number may be. However, for the 40 sake of clearness of description I will describe the mechanism associated with shaft 48 and printing cylinder 21, details of which are illustrated in Figure 7 of the drawings.

Gear 207 is keyed by means of key 208 or 45 otherwise suitably secured to sleeve 209 which is provided with arcuate notch 211 for driving engagement with clutch pin 212. Pin 212 is seated in aperture 213 in hub member 214 of handwheel 216, secured to hub 124 by suitable means as for example bolts 217. Clutch pin 212 extends into radial aperture 218 in sleeve 219. Shaft 48 is provided with a recess 221 and slot 222. An elongated centrally located bore 223 is provided in shaft 48.

Key 224 is seated within recess 221 of shaft 48 for longitudinal reciprocation therein. A projection 226 of key 224 projects through slot or aperture 222, and is received within notch or aperture 227 formed in end 228 of reciprocable 50 rod 229. Key 224 is provided with a spline 231 (Figure 8) of relatively long pitch received in a helical slot 232 of like pitch in the circumferential wall of sleeve 219.

From the parts thus far described, it will be 55 seen that as key 224 is reciprocated in recess 221 by a means to be described, the angular relationship of gear 207 and shaft 48 will be altered. Undesired movements of sleeve 219 on shaft 48 are prevented by collar 234 secured to shaft 48 by suitable means, for example key 236, beyond 60 the point 237 of slight reduction in the diameter of shaft 48. Collar 234 may, if desired, abut inner bearing sleeve 238 which in turn abuts shoulder 239 at the point of reduction in diameter 70 of the shaft 48 thus aiding in preventing longi-

tudinal movement of sleeves 209 and 219 on shaft 48.

Inner bearing sleeves 238 located on the portions of the shaft 48 within frame members 56 and 57 are of a length greater than that of bearings 54 5 and thus permit longitudinal movement of shaft 48 for the purpose of obtaining accurate positioning of impressions from printing cylinders 16, 18, 19 and 21 laterally of web 23 under control of the adjusting means to be described which may be 10 operated under full speed operating conditions of press 11. Bearings 54 and outer bearing sleeve 241 are retained by cover members 242 secured to frame members 64 and 66 by suitable fastening means as for example screws 243. Hand wheel 15 hub body 214, connected for rotation with sleeve 219 by means of pins 246 prevents axial movements of hand wheel hub 214 along shaft 48.

Set screw 247 in hand wheel body 214 frictionally engages groove 248 of clutch pin 212 to hold 20 clutch pin 212 in position with its shank engaged in arcuate notch 211 of sleeve 219 whereby gear 207 may drive shaft 48, or with notch 215 positioned to the left whereby sleeve 209 is free to rotate without imparting rotational movement 25 to sleeve 219.

Any one of printing rolls 16, 18, 19 or 21 may be moved from operative printing position by its associated hand wheel 162 or the printing cylinders may be raised collectively by means of hand 30 wheel 89 without interruption of rotational drive from intermediate gears 191 with clutch 212 in position to engage in arcuate notch 211 in sleeve 209.

By maintaining rotation of the printing cylinders while in their inoperative position, the ink is 35 continuously freshened and maintained at uniform consistency so that the printing cylinders may be moved into operative printing position and print immediately with a supply of fresh ink. 40

Should it be desired to operate the press with less than the total number of printing cylinders clutch pin 212 on those which are idle may be turned so that sleeve 209 may pass freely within 45 groove 215 so that the idle printing roll or rolls are stopped.

The printed impression received on web 23 from any one of the cylinders may be located accurately in a desired position on web 23 by my novel adjusting means about to be described. I 50 have provided novel means whereby the printing cylinders may be moved axially at full operating speeds. Bore 251 of swingable bracket member 187 is provided with threads 252 which engage threaded portion 253 of barrel or sleeve 254. 55 Barrel 254 may be manually rotated by hand wheel 255 for axial movement in bore 251 by engagement of threads 253 and 252. Periphery 255a of hand wheel 255 is provided with graduations, the interval between the graduations corresponding to definite distances measured axially 60 of impression surface 14 and hence transversely of web 23. The graduations may, if desired, correspond to thousandths of an inch as measured on web 23.

Shaft 48 is associated with printing cylinder 16 and is caused to move axially with threaded barrel 254 by anti-friction bearing rings 256 held against axial movement on reduced portion 257 of shaft 48 between collars 258 and 259, 70 mounted on reduced portions 261 and 262 respectively of shaft 48. Collar 259 is in abutting engagement with the edge of hand wheel hub body 214 and clutch sleeve 219. Collar 259 engages sleeve 263 which is secured to the end of the

shaft 48 by suitable means for example set screws 264 which permit collar 263 to be axially adjusted prior to the insertion of set screws 264. Stationary thrust bearing ring 266 engages an annular projection 267 of threaded barrel 254.

Corresponding stationary thrust bearing ring 268 engages a threaded cover or cap 269 the threads of which are in engagement with threads on the interior barrel 254.

10 Suitable anti-friction bearings, for example, balls 273 transmit end thrust of thrust bearing ring 256 to stationary thrust bearing rings 266 and 268. Undesired end play of thrust bearing rings 265, 266 and 268 may be removed by adjustment of threaded cover 269 which may be secured after adjustment by set screws 274.

From the mechanism thus far described it will be seen that as hand wheel 255 is manipulated to move threaded barrel 254 in the desired direction, shaft 48 will be moved axially by means of thrust bearing ring 256 and stationary thrust bearing ring 266 or 268 depending upon the direction of movement for the adjustment desired. Any observed transverse variations on web 23 of the printed impressions from any one of printing cylinders 16, 18, 19 or 21 may be corrected by manipulation of hand wheel 255 associated with the printing cylinder to be adjusted. This may be done at any operating speed or before initial starting of the press. The graduations on hand-wheel 255 facilitate the setting of the printing cylinder to the desired point when out of register. The printed web is measured to determine how much each cylinder is out of register and the hand wheel for that printing cylinder is turned through the number of graduations corresponding to the distance measured on web 23.

As described hereinbefore tail piece 226 of key 224 may be adjusted longitudinally in recess 221 on shaft 48 for the purpose of changing the angular position of gear 207 with respect to shaft 48 so that inaccuracies in location longitudinally of web 23 of the printed impression from the printing cylinder may be corrected and perfect register restored at any speed of the press or with the press at rest. Key 224 may be adjusted longitudinally in recess 221 at any time by manipulation of hand wheel 277 formed on barrel 278. Periphery 277a of hand wheel 277 is also provided with graduations, the interval between the graduations corresponding to definite distances measured longitudinally of web 23. The graduations may, if desired, correspond to thousandths of an inch as measured on web 23. Barrel 254 is provided with an interiorly threaded portion 279 which receives thread 281 on barrel 278. Barrel 278 is rotated by hand wheel 277 to be moved longitudinally with respect to barrel 254. Key 226 and shaft 220, previously described, are moved longitudinally in bore 223 by means of thrust bearing assemblies 283 positioned in barrel 278.

As hand wheel 277 is rotated in either direction barrel 278 will be moved longitudinally with respect to the barrel 254 on threaded connection 281. Thrust bearing assembly 283 will impart the longitudinal movements of barrel 278 to rotatable rod 229.

Thrust bearing assembly 283 comprises rotatable bearing rings 284 and stationary bearing members 286 and 287 between which are interposed suitable anti-friction bearings, for example balls 288. Bearing members are retained on rod 229 by suitable means, for example, cap screw 75 289 and annular member 291.

Thrust bearing assembly 283 is positioned between shoulder 292 and cover plate 293. Cover plate 293 is retained in position by suitable fastening means, for example, cap screw 294. To prevent undesired twisting of rod 230, key 296 may be employed to connect end 262 of shaft 48 to rod 229. 5

Key 296 engages in a flanged web or groove in the end of shaft 48 within collar 263. Suitable means 299 provides for a supply of lubricant to the parts. Lever 301 and clamping bolt 302 may be employed to clamp barrels 254 and 278 in fixed relationship. Links 303 and 304 provide for differences in position of hand wheel 277 and barrel 254. 15

I will now describe the operation of the mechanism including the drives of the several printing cylinders and the register mechanism just described in connection with Figure 5.

Power is applied to main drive shaft 204 (Figure 14) and is transmitted by means of gear 195 to the several intermediate printing cylinder drive gears 191. Each of printing cylinder drive shafts 48, 49, 51 and 52 are mounted in swingable bearing frames 56, 57 and swingable brackets 187. It will be seen that as gears 191 and bearing frames 56 and 57 have a common center, driving force will be applied from intermediate printing cylinder drive gears 191 to printing cylinder drive gears 207 regardless of the angular position of swinging frames 56 and 57, within the limits of their movement. Rotation is thus imparted to printing cylinder shafts 48, 49, 51 and 52 with printing cylinders 16, 18, 19 and 21 either in or out of printing contact with web 23. 30

Ink which may be conveniently supplied from the inking means which are disclosed and claimed in my copending application Serial Number 623,421 filed July 19, 1932 to be described hereinafter thus is continuously supplied to the printing cylinders 16, 18, 19 and 21 both when the several printing cylinders are in operative printing contact with web 23 and also when they are raised out of contact therewith. 35

Should it be observed at any time during operation of the press 11 that the printed impression received on web 23 from any one of the several printing cylinders is out of register laterally with respect to web 23 it may be corrected by manipulation of the hand wheel 277 corresponding to the cylinder to be adjusted. 45

Manipulation of hand wheel 255 moves barrel 254 laterally in the desired direction in bracket 187. Associated printing cylinder shafts 48, 49, 51 and 52 move laterally with barrels 254 by reason of thrust bearing connections 256. The graduations on periphery 255a of hand wheel 255 facilitates accurate setting as has been described. 50

Should it be observed that the printed impression obtained from any one of printing cylinders 16, 18, 19 and 21 is out of its desired position longitudinally of web 23 or that several impressions on web 23 from several printing cylinders are not in exact register or coincidence, accurate and perfect register may be restored under full speed operating conditions of the press by manipulation of hand wheel 277. 60

Manipulation of hand wheel 277 moves key 226 longitudinally of shaft 48. Helical flange 231 in engagement with helical flange web 232 advances over shaft 48 angularly with respect to gear 207 until perfect positioning of the impression received on web 23 from the printing cylinder associated with the particular hand wheel 277 is ob- 70

tained. The graduations on periphery 277a of hand wheel 277 facilitate accurate setting as described above.

It is to be understood that each of printing cylinder shafts 48, 49, 51 and 52 is provided with mechanism including hand wheels 255 and 277, the mechanism associated with shaft 48 being selected as an example of any one of the several printing cylinders.

10 If it is desired at any time to stop rotation of any one of printing cylinders 16, 18, 19 and 21 this may be done by loosening set screw 247 and rotating clutch pin 212 until notch 215 permits free movement of sleeve 209. Sleeve 209 will then 15 rotate idly on sleeve 219 without imparting movement to its corresponding printing cylinder shaft. It is thus possible to print at will from any one of the several printing cylinders or any group thereof. The printing cylinders not in use may 20 remain stationary.

Removal and replacement of the printing shells

As hereinbefore described mandrels or cylinders 16, 18, 19 and 21 may receive movable printing cylinders or shells 22 from which a printed impression or image is made on web 23. To facilitate ready removal or replacement of printing cylinders or shells 22, bearings 53 of shafts 48, 49, 51 and 52 are carried between retractile jaw 30 members 307 in frame member 56.

Retractile jaw members 307 are moved inwardly and outwardly by ring 308 provided with gear teeth 309 on its outer periphery. Volute grooves and teeth 311 interengage with similar 35 grooves and teeth 312 on each of jaw members 307.

Pinion 313 on hand crank shaft 314 may be rotated by means of hand crank 316 to impart rotation to ring member 308 for the purpose of 40 moving jaws 307 toward or from bearing 53.

Bearing shell or ring 318 carries stationary anti-friction bearing member or race 241 and is provided with a groove 319 about its circumference. Jaw 307 when moved toward bearings 53 45 by means of hand crank 316 engages in grooves 319 to form a support for the ends of printing cylinder shafts 48, 49, 51 and 52.

With jaws 307 in their retracted position a free space 321 is provided between rings 318 and 50 swinging frame 56, through which printing cylinders or shells 22 may be passed over ring 318 for removal or replacement on printing mandrels 16, 18, 19 and 21. It will thus be seen that I 55 have provided novel and effective means for applying a shell over a mandrel without removing it from its operative position or disturbing its adjustment or relationship to other parts.

Cover members 322 or 323 retain stationary bearing members 241 of anti-friction bearings 53 60 in position. Suitable fastening means as for example screws 324 retain covers 322 and 323 in position on ring 318.

The mandrels or main printing cylinders

65 Printing cylinder mandrels 16, 18, 19 and 21 illustrated in detail by Figure 11 are provided with novel hydraulic expanding means for retaining printing shells 22 securely in position thereon. The hydraulic method of retaining shells 22 in position can be utilized in forming a printing shell or cylinder by electric deposition merely by first expanding the outer periphery of the mandrel by the novel hydraulic means about to be described and making the deposition on a 70 barrier layer and thereafter contracting the

mandrel to remove the shell bodily as a unit. This will be clear by reference to my above mentioned copending applications.

Reference may now be had to Figure 11 which shows in detail the printing cylinder holder or mandrel to an enlarged scale. I have selected printing cylinder mandrel 16 for the purpose of detailed description shown to the left of Figure 5, which is carried by shaft 48 in the manner illustrated in detail by Figure 7.

External shell 328 is supported on shaft 48 by cylindrical walls 329 over which it may be pressed with a forced fit or otherwise suitably applied so that it will be held firmly in position. An outer expandible shell or cover 331 adapted to be expanded or enlarged by pressure applied to a fluid confined between it and cylinder or shell 328 surrounds cylinder 328. Expandible shell 331 may be of any suitable material. I have found that bronze, preferably centrifugally cast bronze, expands uniformly under the action of fluid pressure on its inner periphery. A helical groove 332 cut or otherwise formed in the surface or shell 328 permits fluid under pressure to be evenly distributed between shell 328 and outer expandible shell 331. It is to be understood that the fluid will not necessarily be confined to helical groove 332, but as outer shell 331 increases in diameter under the influence of applied fluid pressure, said fluid will lie between and fill every part 20 of the space created by uniform expansion radially of shell 331.

Printing cylinders 22 will be held firmly in position without distortion from their desired form by the uniform expansion of outer mandrel shell 331 against their inner surface. The external printing surfaces of printing cylinders 22 will be truly circular at all points and will press with uniform pressure on web 23, a condition which can be realized only by supporting shell 22 without distortion from the desired form.

Outer cylindrical shell 331 is sealed in fluid tight relationship at its ends with cylinders 328 by bands 334. A fluid tight seal is provided by a layer of metal 326 preferably copper. Rings 334 45 may be of any desired cross section. However, if desired their outline in cross-section may be substantially that illustrated on the drawings. It will be seen that a metallic seal of the illustrated cross-section provides effective sealing contact over a relatively large area at and adjacent the ends of cylinders 328 and expandible cylinder 331.

To prepare the outer surface of cylinder 328 to receive expandible cylinder 331, I prefer to apply a coating of metal preferably copper, which may be done by electrodeposition to the outer surface of cylinder 328. The coating of metal on cylinder 328, while not essential is an aid to the uniform distribution of fluid under pressure between cylinder 328 and expandible shell 331. If desired, the inner surface of rings 334 may be supplied with a metallic coating which may be of copper applied by electrodeposition for the purpose of securing an intimate sealing contact in the form of copper seal 326. The copper seal 326 at the ends of the mandrel provides an effective fluid seal which will not leak under any range of fluid pressures necessary or desirable to expand cylinder 331.

Any desired means may be employed to introduce fluid under pressure between cylinders 328 and expandible shell 331.

In the preferred embodiment of my printing cylinder mandrel I employ piston 336 acting in 75

- cylinder 337 situated within bores 338 of shaft 48. Cylinder 337 is retained in position in bore 338 by engagement of threads 339 with threaded portion 341 of bore 338. Piston 336 is advanced 5 along cylinder 337 to compress the fluid therein by means of a rod 342 provided with threads 343 engaging in threaded portion 344 of rotatable member 346.

Rotatable member 346 fits within enlarged portion 341 of bore 338. End thrust of piston 336 on rotatable member 346 is taken up by a thrust bearing which may comprise rings 349 and 351 having suitable anti-friction bearings for example balls 352 to take the thrust of ring 349 relative 10 to ring 351, permitting the rotatable member to be readily turned by means of a wrench or other suitable tool inserted in aperture or socket 353. Sockets 353 may be square in cross-section so as to receive the squared end of a suitable tool or 15 hand crank.

Rotatable member 346 is retained in bore 347 by means of cover member 354, provided with threads to engage threads 356 in the end of shaft 48. Inner surface 357 of cover members 354 cooperates 20 with stationary thrust bearing rings 351 to retain member 346 in bore 347. Suitable means, for example set screws 358, secure member 354 against accidental disconnection from shaft 48. Notches or other suitable means 359 provide for 25 turning member 354 into bore 346.

Piston 336 is provided with an expandible packing 362 adapted to expand against the walls of cylinder 337 as piston 336 is advanced to place the fluid in cylinder 337 under compression. 30 Packing 362 is protected by a cup-like shield 363 which permits packing 362 to be pressed intimately into contact with the wall of cylinder 337 but prevents undue distortion. Packing 362 and shield 363 are held in position by ring 364 and nuts 365 and 367 on threaded stem 368. Leakage of fluid past packing 362 is taken care of by groove 369 and channels 371. Channel 371 provides for escape of any of the fluid which may 35 find its way to bore 344, and so interfere with the movement of stem 342.

Cylinder 337 is provided in its outer wall with circumferential groove 372 and is reduced at its end portion to provide a circumferential space 373 which is in communication with each other and 40 the interior of cylinder 337 by means of longitudinal channel or groove 374. Passage 376 in shaft 48 communicates with passage 374 at a point within the boundary of space 373. Passage 376 is threaded to receive a suitable conduit connection 45 for a purpose to be described.

A passage 377 in shaft 48 communicates with annular groove 372 and passage 374. Opening 377 is provided with suitable threads to receive a threaded plug or other suitable sealing means. 50 It is obvious that if desired a pressure gauge may be connected to passage 377. Passage 378 in cylinder 328 communicates with helical groove 332.

Passage 378 is provided with threads 379 to receive threaded nipple or fitting 381. A bore or 55 passage 382 in valve body or fitting 383 is provided with threads 384 for engagement with the other threaded end of nipple 381. Threads 386 are provided at the external end of passage 387 of valve body 383 for the purpose of receiving conduit 388 composed of suitable fittings. Conduit 388 at its end opposite threaded opening 386 is connected to threaded bore 376 in shaft 48. Passages 387 and 382 are in communication with each other through passage 389 provided with conical 70 valve seat 391.

A chamber or opening 393 is provided in valve body 383. Threads 394 are provided upon the inner wall of valve body 383 at the end of chamber 393. Externally threaded bushings 396 fit within the outer portion of chamber 393 in threaded engagement with threads 394. Externally threaded valve body 397 engages threads on the interior wall of bushing 396 so that it may be adjusted longitudinally of bushing 396.

Valve stem 398 fits within bore 389 and operates with valve seat 391.

Suitable packing 399 is provided about valve stem 398 and is compressed by gland 401 abutting threaded portions 396. Valve 391 may be used to retain fluid placed under pressure by piston 366 within helical groove 332 and thus eliminate the effect of possible leakage in conduit 388 or past piston 366.

Printing cylinder 22 is thus held firmly in position during continued operation of the press independently of any leakage in the main used to supply fluid under pressure to helical groove 332.

Pressure gauge 403 may if desired be connected in threaded passage 404 in communication with helical groove 332. Valve body 383 and fluid connecting conduit 388 are housed within a chamber 406 formed by the portion of cylinder 328 extending beyond wall 329. Chamber 406 is provided with a cover 407 retained in position by suitable fastening means as for example bolts 408, threaded into tapped holes 409 in wall 329. Packing 411 preferably of leather seals chamber 406 at the joints between cover 407 and cylinder 328 and shaft 48. A gland 412 surrounding shaft 48 compresses central packing 411. Access to valve 391 is had through threaded aperture 413 closed by cover 414.

With cover 414 removed a suitable tool may be inserted in aperture 413 to turn valve 397.

With the mandrel just described in operative 40 position on a printing press any desired or selected printing cylinder may be slipped over shell 331 and held firmly thereon by turning rotatable member 346 with a suitable tool inserted in socket 353. Fluid contained in cylinder 337 connecting 45 conduit 388 and helical groove 332 is placed under pressure to expand cylinder 331 into intimate contact with the printing cylinder shell. After desired pressure has been placed on the confined fluid, valve 397 may be closed against valve seat 50 391 to retain the printing cylinder in position firmly for as long as may be desired. The effect of any leakage in the fluid conduit connections and in the piston and cylinder is eliminated.

As hereinbefore described impression cylinder 55 13 rotates freely during normal printing operation, being driven by web 23 which in turn is advanced by the positively driven printing cylinder 16, 18, 19 and 21. It is desirable that impression cylinder 13 be initially started by power driven means and accelerated to normal operating speed thereby to avoid distortion or possible rupture or breakage of web 23 and possible injuries to the etched surface of the printing shell which may result from acceleration of the mass of printing cylinder 13 by frictional contact.

Mechanism for initially starting the impression drum

I will now describe in detail the means for 70 initially starting and accelerating impression cylinder 13 to the desired operating speed. Printing cylinder 13 is supported by hub 417 on shaft 418. If desired the outer drum of printing cylinder 13 may be connected to hub 417 by spokes 419 to 75

achieve a light, but rigid and strong structure. Shaft 418 is provided with enlarged portions 420 over which hub 417 is forced into position on shaft 418 against shoulder 421 which extends through hub 417 in the thin wall section 422 thereof. Shaft 418 is journaled in combined radial and thrust bearings 423 in frame members 38 and 39 respectively. Thrust bearings 423 may if desired be of the type comprised of cup rings 424 and cones 426. It is obvious that any form of anti-friction bearing may be employed. Bearing housing 427 is retained between frame member 38 and cap or cover member 428, secured to frame member 38 by suitable connecting means, for example bolts 429 (Figure 4). Members 426 are retained on the ends of shaft 418 by member 431 secured thereto by suitable fastening means, for example bolts 432. A cover member or ring 433 cooperates with member 431 and is secured to bearing housing 427 by suitable connecting means for example bolts 434. Packing 436 prevents escape or leakage of the lubricant supplied to bearing 423. Covering member 437, retained in position by suitable means as for example bolts 438 in frame member 38 and cap 437 covers and protects bearing 423.

Frame member 39 is also provided with a combined radial and thrust anti-friction bearing to receive the opposite end of shaft 418. Bearing housing 439 is mounted on frame member 39 under cover or cap member 441 which is secured to frame 39 by suitable means 429. A ring 442 secured to bearing housing 439 by suitable means 443 holds packing 444 against shaft 418 to prevent leakage and escape of lubricant. Ring 446 surrounds bearing housing 439 and ring 442 and is secured to frame member 39 and shaft member 441 by suitable means 447.

A dog clutch member or ring 449 is secured to the end of shaft 418 by suitable means 451. As previously described gear 195 is driven from main drive pulley 202 and pinion 203 on main drive shaft 204, as illustrated on an enlarged scale by Figure 14. Gear 195 is keyed or otherwise associated in driving relationship with shaft 197 which is supported in one end by bearing 198 and frame member 39, at the other end by mechanism 199, about to be described in detail.

Anti-friction bearing 198 is protected by cover member 452 secured to frame member 39 and cap 441 by suitable means 453. Cover member 452 contains packing 454.

Hollow shaft 197 at its end opposite bearing 198 is provided with a bearing ring member 456 rotatably secured thereto by key 457. Hollow shaft 197 is rotatably supported through bearing ring 456 and anti-friction bearing 458 on member 459. Member 459 is rotatably supported by anti-friction bearing 461 which is mounted on frame member 41 and held thereon by bearing cap 462 secured to frame member 41 by suitable means 463 (Figure 5). Impression cylinder drive shaft 464 is received at one end within member 459. Suitable means, for example keys 466, in keyways 467 of member 459 and shaft 464 connect shaft 464 rotatively with member 459. Shaft 464 is provided at its ends with splines 468 in engagement with grooves 469 in clutch rings 449 for the purpose of driving impression cylinder 13 when desired through mechanism 199. A clutch comprising splines 468 and member 449 provides a flexible driving connection which permits cylinder shaft 418 to be free from distorting stresses which might otherwise be transmitted from main driving gear 195 and eliminates a pos-

sible source of inaccuracy in the location of impressions received on web 23 from the printing cylinders.

Hub 471 of bevel gear 472 is secured to member 459 by suitable means, for example set screws 473. 5 A shoulder 474 on member 459 rotates hub 473 thereon. A second bevel gear 476 is mounted on shaft 197 and is secured against the hub of gear 195 for rotation therewith by means of set screw 477. Bevel pinion 478 is in mesh with bevel gear 10 472 and 476. Bevel pinion shaft 479 is carried in hub 481 and an aperture in rim 482 of brake drum 201. Pinion shaft 479 is retained in position by suitable means, for example set screw 484. Brake drum 201 is rotatably journaled on hollow shaft 15 197 by means of bearing bushings 486. Suitable means 487 provide for a supply of lubricant to bearing bushings 486.

When desired brake drum 201 is restrained from rotation by brake band 488. Brake band 20 488 is adjusted by means of bolts 489 (Figure 5) and nuts 491 cooperating with ears 492. The ends of brake band 488 are connected to pins 493 in levers 494. Levers 494 are carried on frame member 41 by bolts 496. Arms 495 of levers 494 25 are connected by toggle links 497 so that they may be spread apart to tighten brake band 488 on brake drum 201. Arm 498 of toggle lever 497 may be connected to any suitable operating device or may be provided with a handle for manual operation. 30

I have disclosed by way of example a solenoid magnet 499, core 501 of which is operatively connected by link 502 to lever 498. Pins 503 in frame member 41 serve as stops for levers 494. Impression cylinder 13 may be caused to rotate by drawing plunger 501 of solenoid 499 upwardly. Toggle ears 496 and 497 spread levers 495 which contact brake levers 488 by movement of levers 494 toward each other. 40

Rotation of brake drum 201 is thus prevented and bevel pinion shaft 479 remains stationary. Rotation is then imparted to impression cylinder 13 from gear 195 through bevel gear 476, bevel pinion 478, bevel gear 472 and shaft 464. 45

With brake drum 201 free to rotate, differences in rotational speed between gear 195 and impression cylinder 13 are permitted by rotation of brake drum 201 at some intermediate speed. If, for example, impression cylinder 13 is stationary, 50 brake drum 201 will rotate at the speed of main drive gear 195 due to planetary action of gear 478.

Main drive shaft 204 carrying pulley 202 and drive pinion 203 is journaled in frame members 39 and 41 on anti-friction bearings 506. Bearing 506 in frame member 39 is supported in cup 507 provided with packing 508. A divided collar 509 which is secured together by suitable means 511 retains cup 507 in position on frame 39. Packing 508 is provided for divided ring 509. Divided 60 cover 509 is retained in position on frame member 39 by suitable fastening means for example bolts 512. Bearing 506 in frame member 41 is mounted in cup member 514. A cover plate 516 retains cup member 514 in position on frame 65 member 41. Suitable means 517 connect cover plate 516 to frame member 41.

Access to impression drum

As described hereinbefore impression cylinder 70 13 is provided with a suitable impression surface 14 preferably having a yielding surface such as rubber, which may at times need resurfacing because of damage or natural wear.

I have provided a novel arrangement whereby 75

impression cylinder 13 may be readily made accessible for repair to its surface 14 or for removal bodily if necessary.

Sections 521 and 522 (Figures 4 and 5) of main frame members 38 and 39 respectively are hinged thereto by means of hinge pins 523. As previously described 186 is a detachable portion of frame 41. Cables 524 are connected to movable frame sections 521 and 522 and wound on drum 10 526 within frame members 38 and 39 to which they pass through apertures 527 in frame members 38 and 39 respectively. Guide pulleys or sheaves 529 are elevated above frame members 38 and 39 on upstanding brackets 531 resting on 15 filler blocks 532. Guide pulleys 533 within frame members 38 and 39 guide cables 524 from elevated sheaves 529 to winding drums or winches 526. Winding drums 526 are secured to shaft 534 which may be rotated by worm 536 through worm 20 wheel 537 and gears 538 and 539. Gear 539 is secured to shaft 534 by suitable means for imparting rotation thereto. Worm shaft 541 is provided with a squared end or other suitable means for engagement with a wrench or crank. Should it 25 be desired at any time to have access to impression cylinder 15, it is only necessary to raise movable frame sections 521 and 522 to the position shown on Figure 5 of the drawings by means of winch 526. For this purpose, the link 129 is 30 detached by removal of the bolt 138 securing it in place. It will be seen that substantially a quarter section of the entire press including printing cylinder 21 and its supporting frame 56 and 57 and intermediate driving gear 191 is movable 35 away from its normal position which obstructs access to impression cylinder 13.

Impression cylinders may, if desired, be removed bodily after removal of caps 428 and 441 which retain bearing housings 427 and 439 in 40 position on frame members 38 and 39. If impression cylinder 14 needs only to be resurfaced or ground after removable frame members 521 and 522 are hoisted to the position illustrated by Figure 5, a grinding attachment may be placed 45 on the main frame and the impression cylinder may be ground to a perfect surface in position in the press.

Printing press inking system

50 I will now describe the means for the application of ink to the printing surfaces of printing cylinder 22 or other form of printing device employed on printing cylinders 16, 18, 19 and 21, which means for application of ink is fully disclosed and claimed in my copending application Serial Number 623,421, filed July 19, 1932.

Ink is supplied continuously to the cylinder by means of a distributor 544. Distributor 544 is provided with end portions 546 of cylindrical form that are journaled in bearings 547, Figure 17, secured to frame members 56 and 57, over bosses 548. In this way distributor 544 is swingingly mounted on frames 56 and 57 so that the axis of rotation is disposed relatively close to the 60 surface of printing cylinder 22, and for swinging movement about an axis that parallels the axis of rotation of the cylinder.

65 Portions 546 of the body of distributor 544 are provided with a central longitudinal bore 549 in communication with discharge ducts 551 in the body of distributor 544.

Ink introduced into bore 549 is ejected uniformly through ducts 551 in the body of distributor 544 onto printing cylinder 22. The distributor 70 also includes a wide trough member 553 lap-

ping the rear of its main body portion. A strip 554 of leather or similar soft and pliable material is secured to member 553 in any suitable manner. A sheet metal apron 556 is secured in lapped relation on the outside of distributor 544. Said apron includes an inclined portion serving to house the discharge ducts 551 of the distributor and to direct the liquid discharged therefrom toward member 553 from which it flows in the long V-shaped trough defined between 10 printing cylinder 22 forming one side of said trough and elements 553 and 554 forming the other side, the bottom of the V-shaped trough being formed by the soft and pliable strip 554 which bears lightly upon the surface of printing 15 cylinder 22.

The degree of pressure with which said strip bears upon the cylinder may be varied by shifting the ink distributor just described rotatably about the axis of rotation of the ends 547 by means of 20 a worm wheel 557 secured to one end portion 547 of the distributor. Worm wheel 557 is in engagement with a worm 558 secured to a shaft 559, journaled in ears 561 projecting laterally of the bearing 547. Shaft 559 may be operated by hand 25 wheel 562 to shift the distributor as just stated and thus vary the pressure on strip 554 upon the cylinder.

Ink is supplied to bore 549 by means of conduit 563 that is preferably coiled around one 30 end of the distributor a number of times, the last convolution 564 of said coil being suitably connected by fitting 565 putting said conduit in communication with bore 549.

The excess ink is collected by arranging a casing 35 around the cylinder in position to receive the ink. The casing consists of a main portion 567 in the form of a trough closed at its ends by wall 568 and 569 that laps the ends of cylinder 22 when the casing is in printing position. End 40 walls 568 and 569 are notched at 570 to clear shaft 48 to support the cylinder.

Latches 571 cooperate with pins 572 supported on frames 56 and 57 over bosses 573 by brackets 574. When latches 571 are released from engagement with pins 572 the main portion of the casing 45 may be swung away from the printing cylinder about the portions 547 of the distributor. Said main portion may be readily returned to its operative position and held in proper relation to the cylinder by again engaging the latches with the pins 572 in the manner described in my copending application above referred to. An inclined plate 575 within the main portion 567 of the casing serves to direct ink or cleansing fluid collected thereby toward one corner of the casing where a discharge opening is formed in a tubular extension 576 that is connected to a discharge conduit 577 formed of flexible material so that portion 567 of the casing may be swung 60 upon a pivotal mounting without substantial hindrance from the discharge conduit. A secondary section of the casing may be utilized to further house the inking distributor if desired. Said section 578 may be formed to loosely fit about a 65 part of the cylinder and may include end walls 579 and 581 that form a continuation of end walls 568 and 569 when the secondary section is in operative position. Secondary section 578 is hinged- 70 ly connected to the main section at 582 permitting it to be readily swung to one side when access is desired to the distributor in a manner that will be obvious.

It will be noted that the casing arrangement just described houses the distributor and much 75

of the cylinder 22, the upper edge of secondary section 578 extending relatively close to the doctor blade structure 584. Said structure is mounted on bosses 585 (Figure 10) on frames 56 and 57 and includes a doctor blade 586 and a highly flexible blade 587 arranged to maintain the edge of the doctor blade in firm contact with the cylinder at all points. The doctor blade structure may be rotated bodily in its connection to bosses 10 585 by hand crank 588 through worm 589 and worm wheel 590 so that doctor blade 586 may be moved into and out of contact with printing cylinders 22, and its contact pressure thereon varied. The doctor blade structure may partake 15 of the form described in Patent No. 1,812,920, issued to E. S. Ballard on July 7, 1931, or any other convenient form, such structure per se constituting no part of the present invention.

Ink is continuously supplied to the distributor 20 544 and the surplus that is collected in the casing 567 is returned to the circulating system by coupling supply conduit 563 and discharge conduit 576 to conduit 592 and 593, respectively, in such an arrangement as is illustrated in Figures 17 25 and 18 of the drawings. Referring to these figures an ink reservoir 596, preferably in the form of a cylindrical tank is provided. A shaft 597 carries a plurality of stirring arms that sweep over the bottom of the tank and relatively close there- 30 to to prevent pigment settling at the bottom of the tank. A conduit 599 leads to the intake side of pump 601 supplying either ink taken from tank 596 or cleaning fluid taken from tank 602, the latter being provided for selective or alter- 35 nate use. To this end conduit 599 is in communication with suitably constructed flanges 603 and 604, the former connecting conduits 599 to the ink tank and the latter connecting said conduit to the cleansing fluid tank. A valve 606 in 40 branch 603 and a further valve in branch 604 serves to shut off the flow through said branches when the valves are closed. A two way valve 609 controls the flow from branches 603 and 604 into conduits 599, said valve in one position placing the branch conduit 606 in communication with conduit 599 and in its other position putting branch conduit 604 in communication therewith, the arrangement being such that by manipulation 45 of valves 606, 607 and 609, in a manner that will be obvious, the pump will draw fluid either from tank 596 or tank 602.

The outlet of the pump within casing 611 is in communication with a conduit 612, the flow through which is controlled by valve 613 and 55 which communicates with conduit 592 that leads to the distributor. The conduit 593 receiving the fluid from the casing 567 as above described returns said fluid to either of the tanks 596 or tank 602 through branch conduits 616 and 617 opening into conduit 593. A two way valve 619 controls the flow through the brass conduit in one position putting conduit 593 in communication with branch conduit 616 and in its other position placing the former in communication 60 with a branch conduit 617. The latter opens into tank 62. The branch conduit 616 opens into a casing 621 adjacent the top thereof, though a part of casing 621 is put in communication with tank 596.

In operation of the apparatus above described 70 when the press is set in operation pump 601 is operated causing ink to flow from tank 596 through the distributors, the control valves being set in a manner that will be obvious. The ink 75 is ejected from ducts 551 and flows into the

trough formed between the cylinder and the distributor. In view of the fact that the ducts are arranged to insure supply of ink at relatively closely spaced points, a supply at every point along the length of the trough is provided at all 5 times. The operation of the stir on shaft 597 as well as the continuous circulation of the ink serves to maintain it of precisely the same consistency and keep the pigments in suspension or solution so that an even inking of the cylinders 10 is secured. The printing roll and the inking system can be very conveniently cleaned without disassembly of any parts of the press by simply manipulating the valve 606, 607 and 609 so that the pump circulates cleansing fluid through the distributor and into the trough formed by the distributor and the cylinder. The press is equipped in operation so that the cleansing fluid is supplied to the printing surface in the same way as the ink is distributed thereon. Soft and pliable 20 strips 554 which may if desired be adjusted into firm contact with the cylinder by operation of handle 562 serve to press the cleansing fluid in the minute depressions, thus cleaning the printing surface thoroughly in an extremely 25 simple and efficient manner. When the press is again set in operation the printing system is very easily again put in operation by manipulating the control valve so that the ink is again supplied to the distributor. 30

Variable reciprocation of the doctor blades

It is desirable that doctor blade mechanism 584 of which there is one for each printing cylinder 16, 18, 19 and 21 should be moved longitudinally of the printing surface upon which they rest. Particles of grit may at times become lodged under the edge of the doctor blade and if the doctor blade is not moved longitudinally of the printing surface, repeated passage of the 40 same particle on the printing surface under the doctor blade would cause scoring and damage to the printing surface. It is not only desirable that the doctor blade be reciprocated longitudinally of the printing surface, but in addition it is 45 further desirable that the reciprocation of the doctor blade shall be irregular so that any one point on the doctor blade will not repeatedly pass over a particular part of the area of the printing surface. 50

To the end that each doctor blade may be irregularly reciprocated, I have provided a novel mechanism illustrated by Figures 20 and 21 of the drawings. Motion is imparted from the mechanism of Figures 21 and 22 to each of the 55 doctor blades by the linkage system of Figure 20.

With particular reference to Figures 21 and 22, I will now proceed with the description of my novel mechanism indicated generally by reference character 627, for irregular reciprocation of the 60 doctor blade associated with each of the printing cylinders.

Mechanism 627 comprises a casing formed of two parts or casing halves 631 and 632. Pinion drive shaft 633 to which is secured bevel drive 65 gear 634 is journaled in bearings 636 in housing members 631 and 632. Suitable means, for example pin 637, insures driving connection of bevel drive gear 634 with shaft 633. Bevel gear 634 is in mesh with a bevel pinion suitably set 70 cured to a shaft which is driven by a bevel gear in mesh with pinion 205 on main shaft 204. Double pinion 638 is carried in driving relationship by shaft 633 by means of key 639. Pinion teeth 641 are provided on double pinion 638 for 75

driving engagement with teeth 642 and teeth 643 of gear 644 and gear 645, respectively. Gears 644 and 645 are provided with an unequal number of teeth for a purpose to be described.

5 Gears 644 and 645 are journaled in recesses 651 of the housing in bushings 652. This method of rotatably supporting gears 644 and 645 in housing member 631 and 632 leaves faces 654 of the gears free and provides a space between them. A cam track 656 is provided in gear 644 depressed from its axial face 654 and eccentric with respect to its axis of rotation. Numeral 657 indicates an elongated slot depressed from face 654 of gear 645, extending in a radial direction from a point near the center of face 654.

A connecting rod 661 extends within the space provided between faces 654 of the gears. Cam follower shaft or pin 662 is secured near the end of connecting rod 661 by suitable means as pins 20 663 projecting through connecting rod 661 and cam follower shaft 662.

Followers or rollers 664 and 666 are journaled on shaft 662 and are received in and cooperate with cam tracks or recesses 656 and 657 respectively.

Connecting rod 661 is pivotally articulated to reciprocating cross-head or connecting rod 669 by means of pin 672. Pin 672 is secured to connecting rod 661 by suitable means, as pin 673. 30 Cross-head 669 is mounted for reciprocation through an opening 674 formed by semi-cylindrical recesses in housing members 631 and 632.

Aperture 674 may be sealed against leakage of lubricant by packing 676 and gland nut 677 if desired.

The cross-head or connecting rod 669 is provided with apertured bifurcations 678 at its end for connection to the doctor blade reciprocating linkage to be presently described.

40 The novel mechanical movement just described imparts variable reciprocatory motion to cross-head 669 from connecting rod 661 which carries cam followers or rollers 666 on pins 662. As previously described gears 644 and 645 are provided with an unequal number of teeth and hence rotate at different speeds. The radii of the orbit of movement of rollers 666 in cam groove 651, it will be seen, varies as the roller occupies different parts of the eccentric cam track. Roller 50 666 in elongated cam track 657 causes the roller in cam track 656 to occupy continuously varying positions therein and therefore the radii of the orbit of pin 662 will be continuously varied and hence will cause variable reciprocatory motion 55 to be imparted to cross-head 661.

Variable reciprocatory motion may be imparted to the doctor blades by coupling cross-head 669 to such an arrangement as is illustrated in Figure 20 of the drawings. Referring to this figure 60 a bell crank is provided comprising a shaft 681 mounted in bracket 682. One arm 684 of the bell crank is secured to shaft 681 by suitable means, for example key 686, so as to impart movement to said shaft. Bifurcations 678 of 65 cross-head 669 embrace and are connected to links 688 by a suitable connection, or bolt 692. Link 688 is connected at its opposite end to arm 684 by suitable means as bolt 694.

70 Yoke 696, provided with bearing apertures 693, is secured to shaft 681 for reciprocation therewith. A pin 700 is journaled in aperture 698 of yoke 696 and is retained in position by collar 702 and head 704 apertured to provide a pivotal connection with link 706, which link imparts mo-

tion to shaft 708 through a pivotal connection to an arm formed on or associated with collar 710, which is secured to shaft 708 by pin 712 or other suitable means.

Shaft 708 is journaled in bracket 714 and 716 5 mounted on main frame member 39 and secured thereto by suitable means as bolts 718. Doctor blade operating arm 720 is pinned or otherwise secured for movement with shaft 708 by means of pin 722 inserted in aligned apertures in its 10 housing 724 and shaft 708. A pin 725 is provided at the end of arm 720 for cooperation with one of doctor blade mechanisms 584 in a manner to be described.

An operating arm 720 is associated with each 15 of printing cylinders 16, 18, 19 and 21 and is carried on shafts 726, 728, 708 and 730 respectively. Motion is imparted from shaft 708 which is reciprocated by yoke 696, to shafts 726, 728 and 730 by means of link 732 which is in operative engagement with the several shafts as will be apparent from the description which follows.

Link 732 is pivotally connected to crank arms 734, one of which extends from each of collars 736. Collar 736 of crank 734 is secured to shaft 708 by suitable means, as pins 712. Hub 736 and collar 738 about each side of bearing head 740 of bracket 716, to prevent undesired longitudinal movement of shaft 708. Shafts 726, 728, and 730 are operatively connected to links 732 30 by crank arm 734 extending from collar 736 secured to each of the shafts as illustrated in Figure 20 of the drawings.

Motion imparted from yoke 696 is thus transmitted to arms 720 operatively associated with 35 each of the doctor blade mechanisms. Shafts 726 and 728 are journaled in brackets 742 and 744 secured upon main frame member 39 by suitable means as pins 746. Collar 748 and member 736 cooperate with the bracket to limit 40 undesired end play and movement of the shaft 726. Shaft 730 is made up of two sections 750 and 752 joined by coupling 754, which is or may be secured to each of the sections of shaft 730 by means of set screws 756, permitting ready disconnection of section 752 which is journaled in 45 a bearing aperture in support 758 of bracket 760. Bracket 760 is secured to main frame member 39 by suitable means, as bolts 761.

With section 752 of shaft 730 supported from 50 main frame member 39 as described, sections 521 and 522 of the main frame members may be raised for access to impression cylinder 13 without interference from shaft 730. Should shaft 730 present any substantial impediment to frame members 521 and 522 when they are to be moved, section 752 of shaft 730 may be disconnected at coupling 754.

Each doctor blade 584 is carried by a rod or 60 shaft 768 which may be reciprocated and to which is secured a cam member 770 provided with a groove or circular cam recess 772 (Figure 3) to cooperate with pins or rollers 725 on arm 720. Swinging movement of bearing frames 56 and 57 are accommodated by continued engagement of pin 725 and groove 772 as the printing cylinders are moved into and out of operative position.

Adjustable members are provided comprising 70 rod 774 and heads 776 and 777 which are connected thereto by threaded connections. The socket of head 776 may be provided with right hand threads and the socket of head 777 with left hand threads, making in effect a turnbuckle. 75

Straps 718 and 719 fit over shafts 48 and 49, and are connected to heads 776 and 777 by suitable means, for example bolts 780. The adjustable member to the left of Figure 20 is connected in 5 a similar manner to shafts 51 and 52. Rods 774 are provided at a suitable point with portions 781 formed for cooperation with a suitable wrench or tool. The adjustable members just described are connecting support rods for holding the cylinders, used while the chuck jaws described above 10 which hold the printing cylinder bearing are withdrawn.

From the parts described in connection with Figures 20, 21 and 22 it will be seen that as gear 15 634 is rotated pinion 638 will rotate gears 644 and 645 at unequal speeds because of the different number of teeth on each of the gears. Elongated cam track 657 would cause follower 666 to move in a path or orbit which normally would 20 be substantially circular if the follower were held at the outer end of the groove remote from the center of gear 645. Eccentric cam groove 656 continuously varies the position of cam follower 666 in elongated slot 657 thus causing pin 25 662 to move in an orbit, the radii of which is being continuously varied.

Connecting rod 661 converts the motion of pin 662 to a variable reciprocation which is imparted to cross-head 669.

30 The variable motion of cross-head 669 is translated into a continuously varying oscillatory motion of arm 720 through bell crank arm 684 and link 706, which imparts variable oscillatory movement directly to shaft 708, and by links 732 to 35 the remaining shafts associated with the several doctor blades operative on the printing cylinders.

The surface upon which a printed impression is received from a printing cylinder is preferably treated in a manner to dry the ink, and at the 40 same time avoid distortion of the material printed upon, so that succeeding printed impressions or impression may be superimposed after a relatively brief lapse of time in accurate and perfect registration upon preceding impressions or impression.

45 My novel method and apparatus for drying and treating coated or moist material, a specific embodiment of which is illustrated on Figures 23 and 24 of the drawings, is especially applicable to drying ink on web 23 after each printing from 50 the printing cylinders.

The novel method and apparatus which I am about to disclose and describe in connection with the specific embodiments illustrated on Figures 23, 24 and 25 of the drawings may be used for drying 55 any material which has been coated with a moist substance, for example freshly coated or calendered paper or textiles, or a freshly printed surface and material which has been passed through a treating liquid, for example material having a 60 photographically sensitized surface undergoing development.

Drying apparatus

Referring now to Figure 1, an embodiment 65 782 of my drying and treating apparatus is supported on main frame members 38 and 39 at a position in the illustrated embodiment of the press such that as web 23 progresses beneath a printing cylinder and receives a printed impression therefrom it passes the treating apparatus 782 prior to its passage between the next printing cylinder and impression surface 14. Driers 782 following this plan of disposition in a press are located between each of printing cylinders 16, 18, 70 19 and 21. It is obvious that if desired a drier 75

782 could be mounted from frame members 38 and 39 drying the ink on web 23 after its passage under printing cylinder 21. However, I prefer to pass web 23 through a modified form of my drying and treating apparatus indicated by reference character 784 mounted on top of paper roll stand 12 through which web 23 passes from guide roll 35. It is to be understood that driers 782 and 784 may be used interchangeably if desired, and that while these embodiments thereof are illustrated in connection with the press of my invention, the novel drying method and apparatus about to be described may be used for drying any coated surface, or any material from which moisture is to be removed.

15 I will now describe in detail one of the driers 782 and by way of example will select that one of the driers lying between printing cylinders 19 and 21 which is illustrated in detail on Figures 23 and 24 of the drawings.

20 Referring to these figures, drier 782 comprises an outer casing member 786 formed preferably from sheet metal. Sheet metal partitions 788 and 790 within casing member 786 provide three chambers 792, 794 and 796 respectively. Chambers 794 and 796 are closed at their sides by walls 798 and 800 spaced inwardly from side walls 802 and 804 of outer casing member 786. Chamber 796 includes end compartments 805 and 806. A plurality of nozzle members 808 carried by and 25 suitably secured to bars 810 extend across the bottom of chamber 796 substantially the full width thereof. An external opening 812 is provided in each nozzle member between the in-turned edges 814 for a purpose to be described.

30 Nozzle members 808 are spaced from each other longitudinally of casing member 786 to provide ducts 816 preferably inclined as shown extending substantially the entire width of chamber 794 and said ducts are directly in communication therewith. Similar inclined ducts 818, preferably inclined as shown, are in direct communication with chamber 796. Nozzles 808 are in communication with spaces 804 and 806 of chamber 792.

35 Elongated strips of sheet material 820 having an inturned flange 822 in contact with the end wall of casing member 786 and an inclined lip 826 formed by the inturned edge of casing 786 provides an end nozzle 827. Nozzle 827 is in direct communication by apertures 828 with chamber 792 through passage 830 defined by casing member 786 and partition 788.

40 A similar strip 832 at the opposite end of casing member 786 provides an end nozzle 834 in direct communication by apertures 836 with chamber 792 through passage 830.

45 Plate 840 curved between its ends has flat portions 842 and 844 lying loosely in contact with wall 846 and 848 of partitions 788 and 790 respectively. Walls 848 are suitably notched as at 50 849 to permit them to extend inwardly between strips 810. The ends of flat portion 850 of plate 840 overlies strips 810 and is provided with an elongated slot or aperture 852. An elongated slot 854 is provided in central nozzle 855 with its center substantially in alignment with the center of slot 852.

55 Stiffening member 856 slotted to conform with slot 854 is soldered or otherwise secured to the inside wall of nozzle 855. The parts described 60 are adjustably connected together by suitable means illustrated as bolt 858 in slots 852 and 854. Wing nut 860 engages flat portion 850 of plate 840 to clamp strip 810 between nozzle 855 and plate 840, at the same time bringing plate 840 65 70 75

- in contact with walls 846 and 848 of partitions 788 and 790 to retain them in position. Notches 849 previously described permit walls 846 and 848 to overlie nozzle 855. Conduit connection 864 extends within casing member 786 and communicates with chamber 794. A suitable fitting 866 is provided on conduit connection 864 for connection to conduit 868 connected to a suitable source of cool air.
- 10 Conduit connection 890 extends within the casing member 786 and directly communicates with chamber 796. A suitable fitting 892 is provided for connection with conduit 894 which is connected with a source of heated air. Conduit connection 896 opens directly into space 804 of chamber 792. A suitable coupling member 898 is provided for connection with conduit 900 which is connected to a suitable exhausting apparatus such as a suction fan. Each of the driers 782 is provided with conduit connections just described for connection with conduits which are or may be connected to common sources of cool air, heated air and a common exhausting apparatus, if so desired. The conduit connections to driers 782 lying between printing cylinders 18 and 19 may be connected as illustrated through the wall of casing member 786 opposite nozzle 808. Drier 782 lying between printing cylinders 16 and 18 is supported from frame members 38 and 39 by brackets 904 (Figures 1 and 3). Brackets 904 are secured to main frame members 38 and 39 by suitable means, as bolts 906. Inwardly extending arm 908 of bracket 904 carries a vertically disposed cross-member 910. Cross-members 910 are provided at their ends with upper and lower threaded apertures. Supporting bars 916 and 918 are suitably secured to casing member 786 of drier 782, as for example by a plurality of short bolts 920 secured in sockets 922 which are soldered or otherwise suitably connected to casing member 786. Supporting bar 916 is provided with notches 924 at its end, which notches enable bar 916 to be hung over thumb screw 926. Similar notches 924 are provided in the ends of bar 918 to cooperate with thumb screw 926, by the fastening means just described. Drier 782 is held securely in position in relation to web 23 but may be readily and conveniently removed if desired. Drier 50 782 lying between printing cylinders 19 and 21 is retained in position by bracket 930 similar to bracket 904. Notched supporting bars 916 and 918 are provided which engage over thumb screws 932.
- 55 It will be noted that brackets 930 are secured to main frame members 38 and 39 below the center of impression cylinder 13 so as to lie below swinging portions 521 and 522 of main frame members 38 and 39. Brackets 934, secured to frame members 38 and 39, provide a suitable support for drier 782 located between printing cylinders 18 and 19. Brackets 934 include inwardly extending portions 936 provided with cross pieces 938 which are or may be integral with arms 936. Cross pieces 938 have threaded apertures 940 which are adapted to receive thumb screws 942 which engage notches or apertures in angle member 944 suitably secured to the ends of drier 782, as illustrated on Figure 1 of the drawings.
- 70 In operation driers 782 are connected by conduits to suitable sources of cold air and hot air respectively. Chamber 792 is placed in communication with a suitable exhausting apparatus. The moist surface of material which is to be treated is spaced slightly from the driers 782

so that air blown upon it may act most effectively and as the material is advanced past the drier it first receives a blast of hot air tangentially directed from inclined slots 818 which dries the moist ink. It is obvious that in many specific 5 applications of my novel drier it may be preferable to advance the drier over material under treatment which is held stationary. Slots 818 extend substantially across the full width of the surface to be treated which gives a uniform drying action without causing distortion which would otherwise result.

As the material advances from the zone of warm air issuing from chamber 796 through slot 818, it encounters a tangentially directed blast of 15 cold air issuing from elongated inclined air slots 816. By reason of the uniform distribution of the blast of cold air from slots 816 which extend substantially the whole width of the material being treated, distortion of the material being treated 20 is prevented. Non-uniform shrinkage or expansion of the material under treatment is eliminated by uniform distribution of the hot and cold blasts from my novel drying apparatus.

The surface being treated, after being dried by 25 passage through the zone of heated air encounters the zone of cool air which cools the material under treatment, in this instance the inked surface of web 23 which crystallizes the warm ink so that further printing may be done immediately 30 upon the surface under treatment.

Heated and cooled air blown upon the material under treatment together with fumes which may arise in the case of a moist inked surface coated with volatile inks, are removed through nozzles 35 808, 856 and 826 which quickly remove the warm and cool air and the fumes overlying the surface permitting a successive and continuous application of warm and cold air to quickly dry the ink.

Close and accurate register of succeeding printings is facilitated by my novel method and apparatus for drying the surface of material substantially without distortion and without non-uniform shrinkage or stretching of the material.

A further embodiment 784 of my novel drying apparatus is illustrated on Figures 1 and 25 of the drawings. This embodiment 784 of the drying apparatus is positioned on web roll stand 12 and receives web 23 as it leaves printing cylinder 21 of press 11.

It is to be understood that embodiment 784 of my drier may be used interchangeably with the embodiment 782 illustrated on Figures 23 and 24 of the drawings. Driers such as that indicated by reference character 784 of suitable dimensions may be used to replace driers 782 located between the printing cylinders of press 11.

With particular reference to Figures 1 and 25, I will now proceed with a detailed description of the embodiment 784 of my novel drying and treating apparatus. Outer casing member 952 comprises top wall 954, side walls 956 and end walls 958. Top wall 954 is provided with an opening 960 near one end thereof. End walls or partitions 962 and 964 and partitions 966 and 968 define a recess or chamber 970 in casing member 952 coextensive with aperture 960. A removable cover closes chamber 970 at its top but permits ready access thereto when desired through aperture 960.

A plurality of nozzle members 972 spaced from each other to form ducts or channels 974 which ducts are preferably inclined as shown are secured to longitudinally disposed metallic strips 976 for a purpose to be described. Wall 962 of 75

chamber 970 is turned inwardly at 977 and has a downwardly extending portion 978. Elongated ducts or channels 980 similar to ducts 974 are provided by wall 982 of nozzle member 972 and portion 978 of end wall 962. End wall 964 is turned inwardly at 984 and extends downwardly to provide a downwardly extending portion similar to portion 978 of wall 962. Elongated duct or channel 988 preferably inclined as shown is provided between a wall of end nozzle member 972 and the downwardly extending portion of wall 984. Bars or strips of metallic material 992 rest on inturned portions 977 and 984 of the end walls of chamber 970, and comprise supporting members of a heating unit which may be readily removed from chamber 970 through aperture 960 in casing member 952. Brackets 994 are secured in any suitable manner to strips 992 at conveniently spaced intervals which support heating unit 998 secured to said bracket by suitable means such as screws.

I have chosen to illustrate eleven such heating units, but it is to be understood that the number may vary in accordance with requirements dictated by specific conditions encountered in a particular application.

Space heater unit 998 may be of any well known type, and may if desired be of the type illustrated comprising an insulating strip 1002 surrounded by the convolutions of coils 1004 of electric resistance wires or ribbons, the ends of which are connected to binding post 1006. Binding posts 1006 comprise threaded bolts 1008 over which collar 1010 is clamped by nut 1012. The leads from resistance coil 1004 are received between collar 1010 and nut 1012. Supply lead from a suitable source of electrical energy may be clamped between nuts 1014 and 1016.

Chamber 1018 also within casing 952 is enclosed by end walls or partitions 1020 and 1022 and side walls 1024 and 1026. Nozzle members 972, spaced to form elongated duct or channel 1028, are secured to bars 976 for a purpose to be described hereinafter.

End wall 1022 is turned inwardly at 1030 and extends downwardly at 1032. Elongated duct or channel 1034 is provided by wall 1036 of nozzle 972 and portion 1032 of end wall 1022.

Another duct or channel 1034 preferably inclined as shown is provided by wall 1038 of nozzle 972 and portion 1040 of wall 1020.

Lateral passages 1044 are in communication at their ends with spaces 1046 which extend the length of casing 952 beside chambers 970 and 1018. Walls 1047 of passages 1044 support a plate 1048 provided with upturned lips 1050. Lips 1050 cooperate with lip 1052 on partitions 1020 and 962 to form ducts or nozzles 1053, which communicate with spaces 1046 through passages 1044. Nozzle members 972 are provided with inturned lips 1054 which define elongated nozzles or openings 1055 extending substantially the full length of nozzle members 972 and which communicate with spaces 1046 through the ends of nozzle members 972. End walls 958 of casing 952 are provided with upwardly turned lips 1058 which cooperate with lips 1060 on walls 964 and 1022 to form nozzles or passages 1060 which communicate with spaces 1046 near their ends and also through passages 1062.

Partition 1066, having a portion 1068 in the plane of wall 956, divides conduit connection 1070 into passages 1072 and 1074. Passage 1072 communicates directly with chamber 970. Passage 1074 is in communication with duct 1075 between

walls 956 and housing 1076. Portion 1068 of partition 1066 forms the bottom of passage 1074 and insures that a portion of the air directed into conduit connection 1070 will enter duct 1075. Conduit 1078 provides communication between 5 duct 1075 and chamber 1018. Air, or any desired cooling fluid, is supplied to conduit connection 1070 by a suitable blower.

Conduit connection 1080 is secured in wall 958 and opens directly into one of the spaces 1046 10 which is in communication with passages 1062, 1044 and one end of nozzle 972 as described.

Conduit connection 1080 is adapted for connection with a suction fan or other suitable exhausting apparatus by means of any convenient 15 conduit (not shown).

Suitable flanges or supporting brackets 1082 are provided on casing member 952 whereby it may be mounted on paper roll stand 12 to dry the ink on the surface of web 23 after passage 20 through the last printing couple on press 11.

A separate heater 1084 on paper roll stand 12 lies beneath drier 784. Heater 1084 heats the material of web 23 by contact therewith and assists drier 784 to thoroughly dry the ink on the 25 surface and dry substantially all moisture from web 23 so that it may be rolled or otherwise conveniently disposed of for further handling as a finished printed article. Heater 1084 serves also as a guiding surface to space web 23 slightly 30 from drier 784.

Heater 1084 comprises a frame 1086 having an inwardly directed continuous flange 1088. T-shaped stiffening braces 1090 are suitably connected to flange 1088 at each end in contact with 35 the walls of frame 1086.

A cover plate 1092 overlies frame 1086. Curved ends 1094 of plate 1092 provide smooth guiding surfaces to avoid tearing of web 23.

Electric heaters 1098 which may, if desired, be 40 of the type similar to the heaters described with reference to the chamber 970 are secured to flange 1088 of the heater frame at spaced intervals beneath plate 1092 so that the heat generated may be imparted to cover 1092. I have 45 chosen to illustrate ten such heaters, but it is to be understood that any suitable number may be employed depending upon the degree of heat to be applied and the kind and condition of the material undergoing treatment.

A cooling member 1101 of paper roll stand 12 is located next to heater 1084 beneath chamber 1018 of drier 784. Cooling member plate 1101 is provided with passages 1104 which may suitably communicate at alternate ends to provide a continuous zig-zag passage extending from end to end of the cooling plate. A threaded aperture 1106 is provided in member 1101 to which a pipe 1108 may be connected to conduct cold water through the zig-zag passage formed by passages 1104. 60 A second threaded aperture 1108 provides means for connecting a pipe to drain the cooling fluid from the cooling plate after it has served the purpose of cooling web 23 which overlies the cooling plate. Cooling plate 1101 is mounted on 65 paper roll stand 12 so that web 23 is spaced slightly from duct 1028 and nozzles 1053, 1055, and 1060.

In operation embodiment 784 of my novel 70 drier acts in a manner somewhat similar to that just described for drier 784. Air or other fluid is supplied under pressure through a suitable conduit (not shown) suitably connecting conduit connection 1070 and a blower for example blower 75

110, which may be conveniently mounted on paper roll stand 12.

Conduit connection 1080 is connected with a suction fan or other exhausting apparatus.

5 Web 23 passes under drier 784 and is spaced therefrom a suitable distance by lying over and in contact with heater cover 1082 and cooling plate 1101. The heater and cooling plate are provided to assure the thorough drying of web 10 23 which is desirable before it is finally coiled into a close compact roll or otherwise disposed of for convenient handling.

A portion of the air supplied to conduit connection 1070 enters chamber 970 where it is 15 heated by heaters in chamber 970 before it is blown through duct 980 tangentially onto the moist surface of web 23. Thorough heating of the air and a hot blast on web 23 are assured by having said heaters positioned as illustrated over 20 ducts or channels 980. The heated current of air from channel 980 is distributed uniformly throughout the width of web 23 and dries the moist surface thereof uniformly.

A portion of the air entering conduit 1070 is 25 directed into chamber 1018 through duct 1075, and is projected directly upon the surface of web 23 tangentially thereto through duct 1028 uniformly from edge to edge of web 23. It will be seen that web 23 progresses from a zone to which 30 a blast of heated air is uniformly supplied to a zone to which a blast of cool air is uniformly supplied.

The heated and cooled air blown upon web 23 together with vapor and fumes from the ink being dried is continuously withdrawn through nozzles 1060, 1055 and 1053 so that the current of warmed and cooled air may act most effectively to dry and condition the surface under treatment.

40 In the illustrated embodiment plate 1092 lies sufficiently high with respect to rollers 35 that web 23 is received at curved end 1094 closely against plate 1092 so that the suction created at nozzles 1055, 1053 and 1060 will not lift the 45 material under treatment against the drier and so diminish the effectiveness of the current or blast of air from the drier. If desired the force of the drying current from the drier may be regulated to repel the material under treatment 50 from the face of the drier. The combined effect of the air and suction nozzles is preferably selected so that all of the air projected on the surface to be dried will be removed through the suction nozzles, thus securing a complete removal 55 of the vapor and fumes overlying the surface. This result is secured in the illustrated embodiment by the provision of a greater number of exhaust nozzles with respect to the nozzles for furnishing the drying current.

60 Web roll stand

Web 23, prior to its entry to press 11, is conveniently stored in rolls 24 or 26 which may be supported on web roll stand 12 as shown on Figures 1 and 2 of the drawings. Referring now to the figures it will be seen that web roll stand 11 comprises upright frame members 1111 provided with suitable props 1112 for supporting the drying and cooling apparatus referred to hereinbefore.

70 Frames 1111 are joined by rods 1114 which are suitably provided with threaded end 1116 to receive retaining nuts and washers 1118. Web rolls 26 and 24 are received on shaft 1120 the 75 rotation of which is suitably checked or restrained

by tension means 29 referred to hereinbefore. Shaft 1120 rests in cast bearing or arcuate notches 1122 in removable bearing members 1124 suitably secured to frame members 1111 by fastening means as screws 1126. Rod 1120 is adapted for removal from web roll stand 12 so that it may be inserted through the center opening of the roll of material which is to be fed to press 11.

Shaft 1120 is rotatably secured to the material roll so that it may transmit the turning force 10 of tension means 29 to the roll by means of adjustable conical supporting members 1128 and 1130 provided with conical faces 1132 for wedging engagement with the inner convolution of the roll of material. Member 1128 is movable 15 along rod 1120 to accommodate different widths of material and is secured in its selected position by pawl 1134 which engages in the ratchet teeth of rack 1136. Pawl 1134 is provided with thumb piece 1138 so that it may be turned about pivot 20 pin 1140 to release member 1128 for free longitudinal movement on shaft 1120. The internal bore of member 1130 is provided with threads which engage threaded portion 1142 of shaft 1120 so that it may be moved to the right as 25 illustrated on Figure 2 to firmly secure conical face 1132 thereof against the convolution of the material roll. Member 1130 is split at 1144 so that it may be clamped in position on rod 1120 by screw 1146 situated in recess 1148.

By the means thus provided rod 1120 is compelled to rotate with the material roll as web 23 is continuously fed to press 11 so that the retarding effect of tension means 29 will keep web 23 taut.

35 Tension means 29 comprises brake drum 1150 provided with a central bore to receive reduced ends 1121 of rod 1120. Brake band 1154 encircles drum 1150 and is provided with apertured ears 1156 at its ends so that it may be drawn together against brake drum 1150 by means of rod 1158 and crank 1160. Rod 1158 is provided with threads 1162 which engage in the threaded aperture in hub 1164 of crank 1160. In order that retarding means 29 may be quickly released, 40 lever 1166, having bifurcated end 1168, is provided which embraces the end of rod 1158. Pins 1170 located at a distance from the end of bifurcations 1168 greater than the width thereof 45 pivotally connects throttle lever 1166 to rod 1158. When lever 1166 is turned at right angles to rod 1158 lower ear 1156 is permitted to move toward the edge of bifurcations 1168, thus allowing brake band 1154 to expand quickly.

50 Retarding means 29 is provided for rod 1120 which supports material roll 24.

Guide roller 1174 is provided so that as web 23 is fed to press 11 and the diameter of roll 26 diminishes, web 23 will be kept out of contact with the web roll elevating means to be herein-after described, which is provided to raise rod 1120 and web roll carried thereon to bearing notches 1122.

60 Hoist 1176 comprises sheaves 1178 carried by and rotated with shaft 1180 journaled at one end in bearing 1182 in frame member 1111. Reduced end 1184 of shaft 1180 is journaled in a socket 1186 which is provided in the inner end of crank shaft member 1188 journaled for rotation in member 1111.

70 Gear 1192 and pinion 1196 are keyed or otherwise suitably secured on sleeve 1198 journaled over reduced end 1200 of rod 1202 which is secured at its end in frame member 1111 by suitable nuts 1204. Pinion 1196 drives shaft 1180 75

through gear 1204 rotatably secured to shaft 1180 by key 1206 which also serves to secure one of sheaves 1178 to shaft 1180. Pairs of pulleys 1208 and 1210 of stand 12 are secured to stub shaft 1212 journaled in frame members 1111. Cables 1214 provided with suitable hooks or slings 1216 for engagement with rod 1120 are guided over pulley 1208 and wound on sheaves 1178. With hooks or slings 1216 engaged over shaft 1120 roll 26 may be hoisted by turning hand crank 1220 which is provided with a squared aperture for engagement with the squared end of member 1188. To hoist roll 24 cables 1214 are guided over pulleys 1210 on the opposite side of frame 1111.

15 *Web tensioning means*

Web 23, prior to its entry between the printing couples formed by impression surface 14 and cylinders 22 is guided by pairs of adjustable tension rolls 30—30 and 31—31 mentioned hereinbefore, carried by adjusting means as shown by Figures 3 and 4.

With particular reference now to these figures, brackets 1224 and 1226 are provided and suitably secured to frame members 38 and 39 respectively. Hand wheel shaft 1228 is journaled at 1230 in bracket 1224 and carries gear 1232 and ratchet wheel 1234 suitably secured for rotation therewith. Swingable bearing bracket 1235 is carried 30 at the end of shaft 1236 which is journaled at 1238 in bracket 1224. Shaft 1236 has gear 1240 secured thereon which is in mesh with gear 1232 on hand wheel shaft 1228. Tension guide rolls 30—30 are journaled at their ends in bracket 35 1235 and a similar bracket 1242 which is carried by shaft 1244 journaled in bracket 1226. Gear 1246 is secured to shaft 1244 for rotation therewith. Tension guide rolls 31—31 are journaled at one end in a swingable bracket 1248 rotatable 40 with shaft 1250. Gear 1252 in mesh with gear 1232 is secured on and imparts rotation to shaft 1250. The opposite ends of guide rolls 31—31 are journaled in a swingable bracket 1254 carried by a shaft 1255 similar to shaft 1250 which is 45 journaled in bracket 1226.

Shaft 1255 also carries a gear 1256 which is similar to gear 1252. This gear 1256, and gear 1246 are in mesh with gear 1258 carried by shaft 1260 which is rotatably journaled at 1262 in bracket member 1226.

50 A ratchet pawl 1263 provided with weighted end 1264 is supported on bracket member 1224 and cooperates with ratchet wheel 1234 which is secured to hand wheel shaft 1228.

55 Web 23 is carried over top guide roll 30 and under bottom guide roll 30, and passes over top guide roll 31 and under bottom guide roll 31. By the rotatable means just described for carrying the pairs of guide rolls 30 and 31 upon turning hand wheel 1268 gears 1240 and 1252 are rotated synchronously by gear 1232. Swingable brackets 1235 and 1248 rotate together to alter the angular position of pairs of rolls 30 and 31 to increase or decrease the length of web 23 which is looped over and under the pairs of rolls to increase or decrease the tension thereon. Swingable brackets 1242 and 1254 are constrained to rotate in unison with corresponding brackets 1235 and 1248 by gears 1246 and 1256 which are 65 in mesh with gear 1258, thus preventing distortion or warping of web 23 as it is guided over and under the pairs of tension guide rolls 30 and 31.

70 Hand wheel shaft 1228, after being rotated to the desired position for adjustment of pairs of

tension or guide rolls 30 and 31, is retained in position by pawl 1262 which engages a tooth of ratchet wheel 1234, and is held in engagement therewith by weighted end 1264. To decrease the tension applied to web 23 by the tension guide 5 rolls, it is merely necessary to turn hand wheel 1268 a small amount in a clockwise direction which will release pawl 1262 from the ratchet teeth. Weighted end 1264 may be held in its upper position to prevent engagement of pawl 10 1262 while completing the desired adjustment.

Guide rolls 32, 33 and final guide roll 35 are carried by previously mentioned adjusting means comprising swingable brackets 1272 and 1274 (Figures 1 and 4) carried by shafts 1276 received 15 in bracket 1278, one of which is suitably secured on each of main frame members 38 and 39. Brackets 1272 and 1274 are provided with arms 1281, 1282 and 1284 in which pintles 1286 of guide rolls 32, 33 and 35 are journaled. 20

Hand wheel shaft 1288 is journaled in bracket 1278. A hand wheel 1290 is provided for turning shaft 1288. Hand lever 1292 is connected to shaft 1288 through a pawl and ratchet mechanism, indicated by reference character 1294. 25 Hand lever 1292 cooperates with and may be held in position by member 1296 (Figure 4) fastened to frame member 38 by any suitable fastening means. Brackets 1298 are secured on stub shafts 1276 to impart rotation thereto and are operatively connected by chains 1300 to sprocket 1302 secured to hand wheel shaft 1288 near frame members 38 and 39. 30

Rotation of hand wheel shaft 1288 by manipulation of hand wheel 1290 causes rotation of 35 swingable brackets 1272 and 1274 through chains 1300. Bracket members 1272 and 1274 move in unison by virtue of the duplicate mechanical connection supported by chains 1300 near each end of hand wheel shaft 1288. This arrangement 40 avoids warping or twisting of web 23 and possible undesired sideward displacement as it enters between the printing couples of press 11. To assist in obtaining the desired tension on web 23 hand lever 1292 may be used and final adjustment of 45 tension guide rolls 32, 33 and 35 and levers 1292 may be obtained by engagement with member 1296 to retain the desired adjustment.

50 *Operation*

The operation of my multiple impression printing apparatus will now be described, assuming the parts to be in the position illustrated on Figure 1 of the drawings, but without the presence of web 23 and printing cylinders 22. 55

Impression surface 14 of impression cylinder 13 may be inspected by raising frame members 521 and 522 by manipulation of winch 526, the impression cylinders being rotated manually by hand wheel 206 to facilitate inspection of the 60 entire impression surface. Printing cylinders 22 or other desired printing means or type plates are fitted over printing cylinders 16, 18, 19 and 21 by moving jaw member 307 by means of hand crank 316 (Figure 7) to permit the cylinders to 65 be inserted over bearing members 318 through the peripheral space 321 thus provided as has been described.

Printing cylinders 22 are firmly secured to printing cylinder mandrels 16, 18, 19 and 21 by 70 expanding mandrel shells 331. This operation may be conveniently performed with clutch 212 in a position to permit the printing cylinder mandrel to be rotated freely by hand wheel 216, and with the printing cylinders moved out of engage- 75

ment with impression surface 14. This is readily accomplished by turning handle 89 or by power means provided for such purpose which has been fully described and illustrated.

5 The material of web 23 is threaded into press 11 after inserting it between guide rolls 27 and over guide roll 28 and over and under the various tensioning rolls as previously described, after which it is passed between each one of the printing cylinders and impression surface 14, by rotating the press slowly either by the main power drive or hand wheel 266. After the material has been passed through the impression surface 14 and final printing cylinder 20 it is taken over 10 guide roller 35 and passed under drier 784 on web reel stand 12 as previously described.

After all of the material of the material roll 26 has passed through the press, it is desirable to connect the ends of web 23 which has 15 unrolled from rod 1128 to the ends of the material coiled in roll 24 which may be conveniently placed in position by hoisting it with cable 1214 so that it will be unnecessary to thread the paper or other material upon which it is desired to 20 print through the press each time the supply of material in the roll is exhausted.

It is preferable in event the press is to remain 25 idle for a time that a "dummy" piece of material sufficiently long to extend from roller 27 through the press and under drier 784 be attached to the end of web 23 so that the dummy material may be carried through the guide roll and under the printing cylinders and through 30 drier 784 after which it can be detached from the end of the material which has been passed 35 through the press. Subsequent operation of the press with a fresh piece of paper or other material may be initiated by pasting or otherwise connecting its ends to the dummy strip, where- 40 upon, when the machinery of the press is started, the dummy strip will draw the end of the new material through the guide rolls and the printing couple and under drier 784 and then may be detached from the initial end of the fresh stock 45 and preserved for later use.

With the paper or dummy strip in position power may be continuously supplied to main 50 drive pulley 263 to rotate the printing cylinder mandrels continuously, clutch pins 212 being in their position as previously explained so that the many cylinder mandrels will rotate with gears 207. With the mandrels raised from contact 55 with the sheet of material ready for printing, ink may be supplied to a distributor 578 from supply reservoirs 596 as was fully described in connection with Figures 17 and 18. It is to be understood that in the event that each of the printing cylinders is to be employed to print with inks of different colors in a manner to give color 60 effect by successive superimposed printing, a separate ink supply means including a separate reservoir 596 will be provided for each of the printing cylinders.

When the flow of ink has been properly established to distributor 578, wipers 554 may be adjusted by means of hand crank 562 and doctor blade structure 564 may be adjusted by means of hand crank 568. Hot and cold air respectively is supplied to conduit 894 and 868 and the ex- 65 hausting apparatus connected to conduit 900 is placed in operation. Heating current is supplied to the heaters of drier 784 and to heater 1098 of heated plates 1092. Cold water is supplied to circulate through cooling plate 1101 and air 70 is supplied to the conduit in communication with 75

conduit connection 1070 which also connects to conduit 900.

Before lowering the printing cylinder mandrels to contact with the paper, hand wheels 255 and 277 may be manipulated to position printing cylinder 22 to secure close register of the specific printings of each of the printing cylinders. 5

To initiate printing on web 23 impression cylinder 12 is started and accelerated to normal running speed by tightening band 486 of starting mechanism 199 which will smoothly and rapidly accelerate the impression drum to normal operating speeds at which speed the impression cylinders may be collectively placed in operative contact with the paper by turning hand 15 wheel 89. The brake band of starting mechanism 199 may now be released as impression drum 13 is now being driven by the several printing cylinders overlying the impression surface 14. 10

Close and accurate adjustment of the register 20 of successive printings on web 23 may be made to ensure absolute coincidence of the printing 25 during full speed operation of the press as has been described. Any variation which may be noted from the desired accurate superposition 30 of the printing may be corrected without stopping the press by manipulation of hand wheels 255 and 277. The individual pressure of the 35 printing cylinders on impression surface 14 may be adjusted at any time by rotating worm shaft 141 until proper pressure has been attained. The paper may be fed under proper tension to the 40 press by adjustment of tensioning means 28 and pairs of guide rollers 30 and 31, in conjunction with collective adjustment of guide rollers 32, 34 45 and 35.

Any one of the printing cylinders may be released from contact with impression surface 14 without in any way disturbing the remaining 40 printing cylinders or the pressure of the printing cylinder which is raised by turning key 172 to release worm wheel 157 so that shaft 148 may be rotated by hand wheel 162 to individually raise the printing cylinder from contact with impression rollers 12. As previously described 45 any of the printing cylinders which is raised in this manner is continuously rotating and being continuously supplied with fresh ink to at all times maintain the proper consistency, so that any one of the printing cylinders is ready for 50 immediate use by merely rotating hand cylinder 162 and turning key 172 to engage the hand wheel of worm wheel 157.

From the foregoing disclosure it will be apparent that the methods and apparatus of my 55 invention present means for continuous printing and accurate register of super-imposed impressions under complete control which may be exercised at any time.

The invention may be embodied in other specific forms without departing from the spirit or essential characteristics thereof. The present embodiments are illustrative and not restrictive, the scope of the invention being indicated by the appended claims rather than by the foregoing 65 description, and all changes which come within the meaning and range of equivalency of the claims are therefore intended to be embraced therein.

What is claimed and desired to be secured by 70 United States Letters Patent is:—

1. A printing press comprising an impression means; a plurality of movable printing means spaced along said impression means; means for simultaneously moving said printing means into 75

and out of contact with said impression means; means for independently moving any one of said printing means into and out of contact with said impression means; and a single means for increasing and decreasing the contact pressure between said impression means and said printing means.

2. A printing press comprising an impression means; a plurality of movable printing means spaced along said impression means; means to continuously supply ink to said printing means; means for moving said printing means into and out of contact with said impression means; said ink supply means being operative to maintain said printing means inked when said printing means is in or out of contact with said impression surface and receives any excess ink therefrom whereby said ink supply means supplies continuously fresh ink.

10 3. A printing press comprising an impression means; a plurality of printing surfaces; means to individually adjust said printing surfaces transversely and longitudinally with respect to said impression means; and means to simultaneously move said adjusted printing surfaces into and out of contact with said impression means.

4. In a printing press comprising in combination an impression cylinder and a plurality of printing cylinders, means to adjust the register 30 of each of said printing cylinders, means to disengage one or all of the printing cylinders from operation and again engage said cylinder or cylinders and still maintain the exact register and adjustment as before disengaging.

35 5. A printing press comprising an impression cylinder provided with an impression surface; a plurality of printing cylinders, spaced about the periphery of said impression cylinder in operative contact therewith to form printing couples; a single means to individually adjust the printing pressures of each of said couples; releasable means to permit individual movement of said printing cylinder, and means to collectively move said printing cylinders into and out of contact 40 with said impression cylinder while maintaining the individual adjustment of said adjusting means.

6. In a printing press, an impression cylinder; a plurality of printing cylinders spaced circumferentially around said impression cylinder; means to support one of said printing cylinders in operative relation to said impression cylinder, said means being arranged to be moved and to move said supported cylinder for access to said impression cylinder.

55 7. In a printing press, an impression cylinder; a plurality of printing cylinders spaced circumferentially around said impression cylinder; means to adjust said printing cylinders; and means operatively to support one of said printing cylinders in operative relation to said impression cylinder, said means being arranged to be moved and to move said supported printing cylinder whereby said printing cylinder may be moved aside for access to said impression cylinder while maintaining said adjusting means in adjusted position.

8. In a printing press, an impression cylinder; a plurality of printing cylinders spaced circumferentially around said impression cylinder; means to adjust said printing cylinders; and means to support one of said printing cylinders in operative relation to said impression cylinder, said means being arranged to be moved and to move 70 said supported cylinder whereby said printing

cylinder may be moved aside for access to permit removal of said impression cylinder while maintaining said adjusting means in adjusted position.

9. In a printing press comprising in combination an impression cylinder and a plurality of printing cylinders, means to support a printing cylinder in operative relation to said impression cylinder, and means to bodily remove one of the printing cylinders and its supporting means out of the way so that the impression cylinder can be resurfaced or even removed without disturbing the register and adjustment of said printing cylinder.

10 10. In a printing press an impression cylinder; a movable printing cylinder; means to rotatively drive said printing cylinder; means to move said printing cylinder from operative printing position in contact with said impression cylinder to an inoperative position out of contact therewith, said driving means being effective to drive said printing cylinder in either of its positions and means to maintain said printing cylinder inked in either of its positions without accumulating an excess of ink thereon, whereby the ink on said cylinder may be prevented from drying thereon.

15 11. A printing press comprising an impression means, a plurality of movable printing means spaced along said impression a single means; means individual to each of said printing means for altering the contact pressure on said impression means, a plurality of link members connected for simultaneous operation, each of said link members being connected to one of said means for altering the contact pressure whereby to simultaneously move said printing means into and out of contact with said impression means, and means for individually moving said printing means out of contact with said impression means.

20 12. A printing press comprising in combination an impression cylinder, and a plurality of printing cylinders, each printing cylinder having a single means for adjusting its contact pressure separately, means for simultaneously moving said printing cylinders into and out of contact with said impression cylinder, and means for moving each of said printing cylinders into and out of contact with said impression cylinder individually, said last named means functioning automatically to maintain contact pressure adjustment.

25 13. In a printing press comprising an impression means and a plurality of movable printing means spaced along said impression means, means individual to each of said printing means for imparting movement toward and from said impression means comprising an eccentric mechanism and a link connecting said mechanism to its associated printing cylinder, means for operating said eccentric mechanisms individually, and means for simultaneously operating said eccentric mechanisms whereby said printing means may be simultaneously or individually moved into and out of contact with said impression means.

30 14. The combination of claim 13 with means to indicate graduated movement of each of said eccentric means whereby the pressure of said printing means on said impression means may be adjusted a predetermined amount.

35 15. In a printing press, in combination, a printing cylinder, pivotally mounted supporting means in which said printing cylinder is rotatably mounted, a rotatably mounted shaft, an eccentric on said shaft, means for imparting movement from said eccentric to said cylinder supporting means, a member rotatable on said shaft, means to rotate said member, a toothed mem- 40

ber rotatably secured to said shaft, a worm carried by said rotatable member and engaged with said toothed member to impart rotation from said rotatable member to said shaft and to cause 6 relative rotational movement of said shaft with respect to said rotatably mounted member upon turning of said worm.

16. The combination set forth in claim 15 wherein means are provided for releasing said toothed member from connection with said shaft.

17. In a printing press, an impression cylinder, a frame, a plurality of printing cylinders spaced circumferentially of said impression cylinder, and carried by said frame, and a pivoted section of 15 said frame operatively supporting one of said printing cylinders whereby said printing cylinder may be moved aside for access to said impression cylinder.

18. In a printing press comprising an impression means and a plurality of movable printing rolls, means to move said printing rolls toward and from said impression means comprising a series of toggles arranged to exert maximum force at the relatively extreme positions of said printing rolls, and means to simultaneously actuate 25 said toggles to change the position of said printing rolls.

19. In a printing press comprising an impression means and a plurality of movable printing means spaced along said impression means, means individual to each of said printing means for imparting movement toward and from said impression means comprising an eccentric mechanism and a link connecting said mechanism to 35 its associated printing cylinder, means for operating said eccentric mechanisms individually, and means for simultaneously operating said eccentric mechanisms comprising a series of toggles arranged to exert maximum force at the 40 relatively extreme positions of said printing means.

20. In a printing press, an impression cylinder, a frame, a plurality of printing cylinders spaced circumferentially of said impression cylinder and carried by said frame, said frame comprising a pivoted section arranged to support one of said printing cylinders, and means to move 45 said section whereby said printing cylinder may be moved aside for access to said impression cylinder.

21. In a printing press, a frame, impression means and printing means supported thereby, a section of said frame supporting said printing means being movable to permit removal of said 50

means for access to said impression means on said press.

22. In a printing press, a printing cylinder, a driving connection for said printing cylinder comprising a hollow shaft, a drive member for said shaft having a helical groove therein, a key 5 rotatable with said shaft and engaged in said groove, means in said hollow shaft for moving said key axially to move said shaft angularly with respect to said shaft driving means, and means to shift said shaft axially.

23. In a printing press, a printing cylinder, a driving connection for said printing cylinder comprising a hollow shaft, a drive member for said shaft having a helical groove therein, a key 15 rotatable with said shaft and engaged in said groove, means in said hollow shaft for moving said key axially whereby to move said shaft angularly with respect to said shaft driving means, a member concentric with said shaft with a 20 threaded bore therein, a threaded member in said bore and a thrust connection between said threaded member and said shaft whereby said shaft is moved axially on rotation of said threaded member.

24. In a multi-color printing machine, an impression cylinder, a plurality of printing rolls for said cylinder, said printing rolls frictionally surface driving said impression cylinder, means for moving said printing rolls toward and from 30 said printing cylinder simultaneously and in parallel alinement with said impression cylinder.

25. In a multi-color printing machine, an impression cylinder, a plurality of printing rolls, means for rotating said printing rolls, said printing rolls driving said impression cylinder by frictional surface contact, means for moving simultaneously all of said printing rolls from said printing cylinder to stop the printing and wastage of material being printed, and means for separately adjusting any one of said rolls.

26. In a multi-color printing machine, an impression cylinder, a plurality of printing rolls frictionally driving said printing cylinder, means for individually inking each of said printing rolls, means for simultaneously moving all of said printing rolls from said cylinder to cease printing and stop wastage of material upon which the printing is being done when adjustment is required on any one roll and for simultaneously moving all of said printing rolls to said cylinder when said adjustments have been made in order to resume printing at the place where the printing was stopped.

EMIL ERICKSSON.
